[57] ABSTRACT

The frequency-sensing circuit of a paper currency validator uses fixed, rather than adjustable, components to sense a predetermined frequency; and an adjustable speed D.C. motor is set to drive the vertical grid lines in the portrait background of a bill past the air gap of a magnetic head at a selected rate to develop signals of that predetermined frequency. That frequency-sensing circuit is much more stable and much less expensive than a frequency-sensing circuit which uses adjustable components, and that D.C. motor is much smaller and much less expensive than a synchronous motor of comparable power. That D.C. motor causes bill-driving members to move a bill past a bill-actuated switch and then past that magnetic head; and a timing circuit will reverse that motor, to cause those bill-driving members to move that bill back outwardly of that paper currency validator, if that magnetic head does not coact with the frequency-sensing circuit to develop a validation signal within a predetermined length of time. A sub-circuit senses the current flowing to the motor; and, if a person attempts to retard or halt the inward movement of a bill, the value of the motor current will increase, and the cur-

rent-sensing sub-circuit will respond to the increase in motor current to inhibit the development of a validation signal. The paper currency validator has a bill-actuated start switch, a bill-actuated sequence switch and a bill-actuated exit switch; and those switches are normally connected to the rest of the circuitry of that paper currency validator. However, as soon as a validation signal is developed, all of those switches are immediately isolated from the rest of that circuitry; and this is desirable, because it keeps any further closing of any of those switches from affecting the rest of that circuitry. In this way, any undesirable effect from "contact bounce" or from the deliberate closing of any of those switches is completely obviated. If a person attempts, in an unauthorized manner, to cause the paper currency validator to supply a vend signal, the motor of that paper currency validator will automatically reverse and thereby cause the bill-driving members to return to that person any bill or other object which was being used in that attempt. In addition, that paper currency validator will cancel any validation signal which had been developed as a result of the insertion of that bill or other object. The paper currency validator disposes one magnetic head so it can sense the vertical grid lines in one quadrant of the portrait background of a bill and disposes a second magnetic head so it can sense the vertical grid lines in the diagonally-displaced quadrant of that portrait background; and it requires those magnetic heads to simultaneously supply signals of essentially the same frequency. The paper currency validator disposes bill-driving members immediately outwardly of the first magnetic head and it also provides a sub-circuit which will reverse the motor if the leading edge of a bill is not able to move a fixed distance beyond that magnetic head within a predetermined length of time. Because those bill-driving elements are disposed immediately outwardly of that magnetic head, they will remain in engagement with the trailing edge of that bill even if substantially the entire length of that bill is wrinkled and crumpled up against that magnetic head; and that sub-circuit will reverse the motor, and thereby enable the bill-driving members to move that bill back outwardly of the paper currency validator, before those bill-driving members could tear or otherwise degrade that bill.

PAPER CURRENCY VALIDATOR

SUMMARY OF THE INVENTION

This invention relates to improvements in paper currency validators. More particularly, this invention relates to improvements in paper currency validators wherein the movement of an authentic bill past a sensing device will develop signals having a predetermined frequency.

It is, therefore, an object of the present invention to provide an improved paper currency validator which develops a predetermined frequency as an authentic bill is moved past a sensing element.

Prior paper currency validators, which moved bills through them at predetermined rates to develop signals of predetermined frequencies, used synchronous motors to drive those bills; and they used adjustable components in the frequency-sensing circuits thereof to make the center frequencies of those frequency-sensing circuits match those predetermined frequencies. However, adjustable inductors are less stable and more expensive than fixed inductors of comparable quality, and adjustable capacitors are less stable and more expensive than fixed capacitors of comparable quality; and hence paper currency validators which use frequency-sensing circuits that utilize adjustable components are less stable and more expensive than would be a paper currency validator which uses a frequency-sensing circuit that utilizes fixed components.

The paper currency validator of the present invention is able to use a frequency-sensing circuit which utilizes fixed components because it utilizes an adjustable speed D.C. motor that has the speed thereof closely regulated. That adjustable speed D.C. motor is adjusted to drive the vertical grid lines in the portrait background of a bill past the air gap of a magnetic head at a rate which will enable that magnetic head to develop signals which have a frequency that matches the frequency of the frequency-sensing circuit of that paper currency validator. The present invention thus makes the speed of the adjustable speed D.C. motor thereof a function of the frequency of the frequency-sensing circuit thereof rather than vice versa; and, in doing so, that paper currency validator makes it possible to use a much more stable but much less expensive frequency-sensing circuit, and also makes it possible to use a much smaller and much less expensive motor. It is, therefore, an object of the present invention to provide a paper currency validator with an adjustable speed D.C. motor which can move bills through that paper currency validator at a rate which is a function of the center frequency of a frequency-sensing circuit that uses fixed components.

The D.C. motor of the paper currency validator of the present invention causes bill-driving members to move a bill past a bill-actuated switch and then past a magnetic head; and a timing circuit will reverse that motor, to cause those bill-driving members to move that bill back outwardly of that paper currency validator, if that magnetic head does not coact with the frequency-sensing circuit to develop a validation signal within a predetermined length of time. In doing so, that timing circuit keeps the bill from moving so far inwardly of the paper currency validator that the bill-driving members would be unable to move that bill back outwardly of that paper currency validator. Also,

in doing so, that timing circuit limits the length of time during which that bill is adjacent that magnetic head, and thereby correspondingly reduces the likelihood that a person could manipulate that bill and cause it to coact with that magnetic head to develop signals of the required frequency. It is, therefore, an object of the present invention to provide a paper currency validator wherein a motor causes bill-driving members to move a bill past a bill-actuated switch and then past a magnetic head, and wherein a timing circuit will reverse that motor, to cause those bill-driving members to move that bill back outwardly of that paper currency validator, if that magnetic head does not coact with the frequency-sensing circuit to develop a validation signal within a predetermined length of time.

The motor of the paper currency validator of the present invention causes the bill-driving members thereof to move at a fixed rate of speed; and, once that motor has gotten those bill-driving members up to that rate of speed, it will draw an approximately constant value of current. That motor and those bill-driving members will resist any efforts of a person to retard or stop the movement of a bill inwardly of the paper currency validator; and, in doing so, that motor will draw increased values of current. A sub-circuit senses the value of the current drawn by the motor; and, if a person attempts to retard or halt the inward movement of a bill, that sub-circuit will respond to the consequent increase in the value of the motor current to inhibit the development of a validation signal. This means that if a person was able to retard or stop the inward movement of a bill, that person would not be able to effect the unauthorized vending of a product from the vending machine, to which the paper currency validator is connected, because the current-sensing sub-circuit would prevent the development of a validation signal. It is, therefore, an object of the present invention to provide a paper currency validator with a current-sensing sub-circuit which will respond to undue increases in the value of the motor current to inhibit the development of a validation signal.

The paper currency validator of the present invention has a bill-actuated start switch, a bill-actuated sequence switch and a bill-actuated exit switch; and those bill-actuated switches are normally connected to the rest of the circuitry of that paper currency validator. However, as soon as a validation signal is developed, all of those bill-actuated switches are immediately isolated from the rest of that circuitry; and this is desirable, because it will keep any further closing or opening of any of those switches from affecting that circuitry. In this way, any undesirable effects on the operation of the rest of that circuitry, which are due to "contact bounce" or to the deliberate closing and opening of any of those switches, will be obviated. It is, therefore, an object of the present invention to provide a paper currency validator which has bill-actuated switches that are initially connected to the rest of the circuitry of that paper currency validator but which are immediately isolated from the rest of that circuitry as soon as a validation signal is developed.

If a person inserts a short length of a bill into the paper currency validator of the present invention, attaches a tape, thread or other "tail" to a bill, disconnects and then reconnects the line cord of the paper currency validator, or otherwise attempts to obtain an improper operation of that paper currency validator,

the motor of that paper currency validator will reverse and thereby cause the bill-driving members to move any inserted bill or the like back outwardly of that paper currency validator. In addition, that paper currency validator will automatically cancel any validation signal which was previously developed as the cropped bill or tail-equipped bill was moved inwardly of that paper currency validator. In this way, the present invention returns all cropped bills and tail-equipped bills — so other persons can subsequently insert proper bills; and it also automatically cancels any validation signal which that cropped bill or tail-equipped bill might have developed. It is, therefore, an object of the present invention to provide a paper currency validator which can return all cropped bills or tail-equipped bills by reversing the motor thereof, and which will automatically cancel any validation signal which that cropped bill or tail-equipped bill might have developed.

The paper currency validator of the present invention disposes one magnetic head so it senses the vertical grid lines in one quadrant of the portrait background of a bill and disposes a second magnetic head so it senses the vertical grid lines in the diagonally-displaced quadrant of that portrait background. In addition, that paper currency validator will provide a validation signal only if both of those magnetic heads simultaneously sense vertical grid lines of predetermined spacing within those diagonally displaced quadrants of the portrait background. By disposing the two magnetic heads so they must sense vertical grid lines in diagonally-displaced quadrants of the portrait background of a bill, the paper currency validator of the present invention avoids the development of a validation signal in the event a person inserts just the upper half, just the lower half, just the left-hand half, or just the right-hand half of a bill. By requiring the two magnetic heads to simultaneously sense vertical grid lines of predetermined spacing within the diagonally-displaced quadrants of the portrait background of each bill, the paper currency validator avoids the cost and space of the sub-circuit which would be needed to hold a first frequency-initiated signal until a second frequency-initiated signal was developed. It is, therefore, an object of the present invention to provide a paper currency validator which disposes one magnetic head so it will sense vertical grid lines in one quadrant of the portrait background of a bill, to mount a second magnetic head so it will sense vertical grid lines in the diagonally-displaced quadrant of that portrait background, and to develop a validation signal only if those magnetic heads simultaneously sense vertical grid lines of predetermined spacing within those diagonally-displaced quadrants.

The paper currency validator of the present invention disposes some bill-driving members thereof immediately outwardly of a magnetic head thereof, and provides a sub-circuit which will reverse the motor thereof if the leading edge of any bill does not move a fixed distance inwardly of that magnetic head within a predetermined length of time. The bill-driving members are spaced so close to that magnetic head that even if no portion of that bill is able to pass by that magnetic head — and hence substantially all portions of the length of that bill become wrinkled and crumpled up adjacent that magnetic head, those bill-driving members will still be in engagement with the trailing edge of that bill. The

sub-circuit will promptly reverse the motor and cause the bill-driving members to move the bill back outwardly of the paper currency validator — thereby clearing the paper currency validator so further bills can be accepted by it. That sub-circuit will reverse the motor and cause the bill-driving members to move the bill back outwardly of the paper currency validator before those bill-driving members would have time to tear or otherwise degrade the bill. It is, therefore, an object of the present invention to provide a paper currency validator which disposes some bill-driving members thereof immediately outwardly of a magnetic head thereof and which provides a sub-circuit that will reverse the motor thereof if the leading edge of a bill does not move a predetermined distance inwardly of that magnetic head within a predetermined length of time.

Other and further objects and advantages of the present invention should become apparent from an examination of the drawing and accompanying description.

In the drawing, FIG. 1 is a perspective view of one preferred embodiment of paper currency validator that is made in accordance with the principles and teachings of the present invention.

FIG. 2 is a partially-broken elevational view of the front of the paper currency validator of FIG. 1, FIG. 3 is an elevational view of the rear of the paper currency validator of FIG. 1, FIG. 4 is a sectional view through the paper currency validator of FIG. 1, and it is taken along the plane indicated by the line 4—4 in FIG. 2,

FIG. 5 is another sectional view through the paper currency validator of FIG. 1, and it is taken along the plane indicated by the line 5—5 in FIG. 2, FIG. 6 is a bottom view of the cover and associated parts of the paper currency validator of FIG. 1, and it is taken along the plane indicated by the line 6—6 in FIG. 3,

FIG. 7 is a partially broken-away, plan view of the paper currency validator of FIG. 1 with the cover and associated parts removed, and it is taken along the plane indicated by the line 7—7 in FIG. 5, FIG. 8 is a bottom view of a portion of the paper currency validator of FIG. 1, and it is taken along the plane indicated by the line 8—8 in FIG. 5,

FIG. 9 is a sectional view through one of the pressure rollers, and is an end elevational view of one of the magnetic heads, of the paper currency validator of FIG. 1, and it is taken along the plane indicated by the line 9—9 in FIG. 10,

FIG. 10 is a side elevational view of the magnetic head and of the pressure roller shown in FIG. 9, The diagram at the right of FIG. 10 shows the manner in which FIGS. 11, 12 and 13 can be associated either with FIG. 14 or with FIG. 15,

FIG. 11 is a schematic diagram of part of the overall circuitry of the said one preferred embodiment of paper currency validator.

FIG. 12 is a schematic diagram of another part of that overall circuitry.

FIG. 13 is a schematic diagram of a further part of that overall circuitry.

FIG. 14 is a schematic diagram of the remaining part of that overall circuitry, and

FIG. 15 is a schematic diagram of a sub-circuit which can be substituted for the sub-circuit shown in FIG. 14.

DESCRIPTION OF THE PREFERRED EMBODIMENT

Referring to the drawing in detail, the numeral 30 generally denotes one preferred embodiment of paper currency validator that is made in accordance with the principles and teachings of the present invention. The numeral 32 denotes a platform which extends outwardly from the front of the paper currency validator 30; and that platform will receive the leading edge of each bill which is to be tested by that paper currency validator. Flanges 34 and 36, of generally triangular configuration, extend upwardly from the sides of the platform 32; and that platform has an upwardly-inclined inner end 38 which merges into a platen 40 of rectangular configuration as shown by FIGS. 4 and 5. An elongated flange 42 extends downwardly from each of the elongated sides of the platen 40; and the numeral 44 denotes ears which extend laterally outwardly from the front ends of the flanges 42. The numeral 45 denotes the trailing edge of the platen 40; and, as indicated by FIGS. 4 and 5, that trailing edge inclines downwardly and then terminates in a vertically-directed lip. As indicated by FIG. 7, the platen 40 has three rectangular slots 46, 48 and 50 in alignment with each other adjacent one side thereof; and that platen has rectangular slots 56, 58 and 60 in alignment with each other adjacent the opposite side thereof. The slot 56 is in register with the slot 46, the slot 58 is in register with the slot 48, and the slot 60 is in register with the slot 50; and the rear ends of the slots 50 and 60 are cut away, as shown by FIG. 7. The platen 40 also has a narrow elongated slot 52 therein which has semi-circular ends; and that slot is located between the slots 46 and 56 but is closer to the slot 46 than it is to the slot 56. A similar slot, not shown, also is located between the slots 46 and 56, but it is closer to the slot 56 than it is to the slot 46. The numeral 54 denotes a slot in the platen 40 which is adjacent the trailing edge 45 of that platen; and that slot is closer to the slot 60 than it is to the slot 50. The platen 40 has two additional slots, not shown; and one of those slots accommodates the upper portion of a roller 102 while the other of those slots accommodates the upper portion of a roller 114. Those rollers are indicated by solid lines in FIG. 5 and by dotted lines in FIG. 7.

The numeral 62 denotes a headed pin which has the shank thereof fixedly secured to the left-hand flange 42 of the platen 40, as the paper currency validator is viewed in FIG. 2. As shown by FIGS. 4, 5 and 7, that pin is adjacent the front of that paper currency validator. The numeral 64 denotes an elongated pivot which extends between, and which is supported by openings in, the downwardly-directed flanges 42 on the platen 40; and that pivot is disposed inwardly of the headed

pin 62. The numeral 66 denotes a headed pin which can be identical to the headed pin 62, and that headed pin has the shank thereof fixedly secured to the left-hand flange 42 of the platen 40. The headed pin 66 is close to the rear of the paper currency validator, as shown by FIGS. 4 and 5. A headed pin 68 has the shank thereof secured to the right-hand flange 42 of the platen 40, as the paper currency validator is viewed in FIG. 2; and that headed pin is in register with the headed pin 62. A further headed pin, not shown, is secured to that right-hand flange; and that headed pin is in register with the headed pin 66.

The numeral 70 denotes a leaf-type spring which is bent so the right-hand end thereof inclines upwardly and to the right in FIG. 4 to bear against the under surface of the platen 40. That spring also is bent to have a downwardly-opening saddle, to have an elongated portion which inclines upwardly and to the left in FIG. 7 from that saddle, and to have a bifurcated left-hand end with fingers that define an upwardly-opening saddle. The numerals 72, 74, 76 and 78 denote springs which can be identical to the spring 70; and, as indicated by FIGS. 4 and 5, the spring 72 is adjacent the front of the platen 40 and the spring 74 is adjacent the trailing edge 45 of that platen. The spring 76 is in register with the spring 72, as indicated by FIG. 2; and the spring 78 is in register with the spring 74, as indicated by FIG. 3. A further spring, not shown, is in register with the spring 70. The downwardly-opening saddles of the spring 72, 74 and 76 telescope down over, and are supported by, the headed pins 62, 66 and 68, respectively; and the downwardly-opening saddles of the spring 70 and of its counterpart telescope down over, and are supported by, the opposite ends of the pivot 64, while the downwardly-opening saddle of the spring 78 telescopes down over, and is supported by, the counterpart of headed pin 66.

A short pivot 80 is supported by the upwardly-opening saddle which is defined by the fingers at the bifurcated end of the spring 72; and that pivot rotatably supports a roller 82. A similar pivot 84 is supported by the upwardly-opening saddle which is defined by the fingers at the bifurcated end of the spring 70; and that pivot rotatably supports a roller 86. Another similar pivot 88 is supported by the upwardly-opening saddle which is defined by the fingers at the bifurcated end of the spring 74; and that pivot rotatably supports a roller 90. The numeral 92 denotes a roller which is rotatably mounted on a pivot, not shown, that is supported by the upwardly-opening saddle which is defined by the fingers at the bifurcated end of the spring 76. The numeral 93 denotes a roller which is in register with the roller 86 and which is held by a short pivot, not shown, that is supported by the upwardly-opening saddle which is defined by the fingers at the bifurcated end of the spring, not shown, which is the counterpart of the spring 70. The numeral 94 denotes a short pivot which is held by the upwardly-opening saddle which is defined by the fingers at the bifurcated end of the spring 78, as shown by FIG. 3; and a roller 96 is rotatably mounted on that pivot. As shown by FIG. 7, the upper portions of the rollers 82, 86 and 90 are disposed, respectively, within the slots 46, 48 and 50 in the platen 40; and the upper portions of the rollers 92, 93 and 96 are disposed, respectively, within the slots 56, 58 and 60 in that platen. As indicated by FIG. 4, the springs 70, 72, 74, 76 and 78 and the spring, not shown, which is the

counterpart of spring 70 urge the rollers 86, 82, 90, 92, 96 and 93, respectively, upwardly relative to the platen 40. However, those springs can yield to permit those rollers to be moved downwardly.

The numeral 98 denotes an arm which has a hub that encircles the pivot 64, as indicated by FIG. 8. A pivot 100 is fixedly secured to the outer end of the arm 98, and that pivot rotatably supports the roller 102. As shown by FIG. 9, the opening through that roller has a frusto-conical portion 104 and a frusto-conical portion 106. Those frusto-conical portions enable the roller 102 to tilt relative to the axis of the pivot 100; and a C-washer 103 holds that roller against accidental separation from that pivot. The numeral 110 denotes an arm which has a hub that also encircles the shaft 64; and, as indicated by FIG. 8, the hubs of the arms 98 and 100 confront each other and space those arms apart. A pivot 112 is fixedly secured to the outer end of the arm 110; and that pivot rotatably supports the roller 114. The opening through the roller 114 is defined by two frusto-conical portions in the same manner in which the opening through the roller 102 is defined by two frusto-conical portions. A C-washer 108 is mounted on the pivot 112, and it prevents accidental separation of the roller 114 from that pivot. A torsion spring 116 encircles the hubs of the arms 98 and 110; and one end of that torsion spring is hooked through an opening in the arm 98, while the other end of that torsion spring is hooked through an opening in the arm 110. That torsion spring urges both the roller 102 and the roller 114 upwardly relative to the openings, not shown, which are provided in the platen 40 in register with those rollers. However, that torsion spring can yield to permit those rollers to be moved downwardly relative to that platen.

The numeral 118 denotes an upper platen which normally is disposed in parallel relation with, and in close proximity to, the platen 40. The platen 118 has downwardly-directed flanges 120 at its sides thereof, and each of those flanges has a downwardly-opening slot 122 adjacent the forward end thereof. Those slots are dimensioned and disposed to accommodate the outwardly-extending ears 44 at the front ends of the flanges 42 on the lower platen 40. The numeral 124 denotes the semi-cylindrical leading edge of the platen 118; and that semi-cylindrical leading edge is disposed forwardly of the upwardly-inclined rear portion 38 of the platform 32, as indicated by FIGS. 4 and 5. That semi-cylindrical leading edge will coat with the upwardly-inclined rear portion 38 of the platform 32 to provide a desired smoothing and flattening out of any longitudinally-extending wrinkles, creases or folds in bills which are introduced into the paper currency validator 30. The platen 118 has an upwardly-inclined trailing edge 126, as indicated by FIGS. 3-5.

An elongated slot 128 which has semi-circular ends is provided in the platen 118 adjacent one side of that platen; and that slot overlies the rollers 82, 86 and 90. That slot extends from a point which is slightly outward of the roller 82 to a point which is slightly inward of the roller 90. A similar elongated slot 130 is provided in the upper platen 118 adjacent the opposite side of that platen; and that slot overlies the rollers 92, 93 and 96. The slot 130 extends from a point which is slightly outward of the roller 92 to a point which is slightly inward of the roller 96. The numeral 132 denotes a narrow elongated slot in the platen 118 which has the same

configuration as the slot 52 in the platen 40; and those slots will be in vertical registry whenever those platens are in the positions shown by FIGS. 4 and 5. The numeral 134 denotes a slot in the platen 118 which is identical to the slot 132; and that slot will be in vertical registry with the slot in the platen 40 which is identical to the slot 52 but which is closer to the slot 56 than it is to the slot 46. The numeral 136 denotes a slot which is generally in registry with the slot 54 in the platen 40; and that slot is closer to the slot 130 than it is to the slot 128. Two additional slots, not shown, are provided in the platen 118; and one of those slots is in register with the roller 102, while the other of those slots is in register with the roller 114. Those two additional slots are shorter than, but are wider than, the rollers 102 and 114. The platen 118 also has two openings, not shown, which accommodate the lower faces of magnetic heads 208 and 210; and those openings are in register with the rollers 102 and 114. Whenever the platens 40 and 118 are in the positions shown by FIGS. 4 and 5, the torsion spring 116 will urge the upper portions of the rollers 102 and 114 against the air gaps of the magnetic heads 208 and 210, respectively. If, for any reason, the axis of the pivot 100 is not precisely parallel to the air gap of the magnetic head 208, the frusto-conical portions which define the opening through the roller 102 will enable the portion of that roller which engages that magnetic head to respond to the force which is applied by the spring 116 to move into precise parallelism with that air gap. Similarly if, for any reason, the axis of the pivot 112 is not precisely parallel to the air gap of the magnetic head 210, the frusto-conical portions which define the opening through the roller 114 will enable the portion of that roller which engages that magnetic head to respond to the force which is applied by the spring 116 to move into precise parallelism with that air gap. This is important; because it enables the rollers 102 and 114 to assure full line contact between inserted bills and the air gaps of the magnetic heads 208 and 210 — even where a light-pressure torsion spring 116 is used to reduce the resistance which the rollers 102 and 114 will offer to the leading edges of inserted bills.

The numeral 140 denotes a cover for the paper currency validator; and that cover has downwardly-directed flanges 142 at the sides thereof. Each of the flanges 142 has a lateral offset therein, as shown by FIGS. 1-3; and the cover 140 preferably is coextensive with the upper platen 118, as indicated by FIGS. 4 and 5. The numeral 144 denotes a switch bracket which is secured to the cover 140, as shown by FIG. 5; and that switch bracket holds a switch 146 adjacent the front of the platen 118. The numeral 148 denotes a sturdy but thin actuator for the switch 146; and that actuator has a leading edge 150 and a trailing edge 152 which extend downwardly through the slots 132 and 52, respectively, in the platens 118 and 40. As indicated by FIG. 5, the leading edge 150 is essentially straight, and it inclines downwardly from the upper left to the lower right whenever the actuator 148 is in its normal position. The trailing edge 152 is convex, and it inclines downwardly from the upper right to lower left whenever the actuator 148 is in its normal position. The configurations and inclinations of the leading and trailing edges 150 and 152, respectively, of the switch actuator 148 enable the leading edge and trailing edge, respectively, of a bill to engage the leading edge 150 and the

trailing edge 152 and easily raise that actuator upwardly out of the slot 52 in the platen 40. As a result, the switch actuator 148 permits relatively free movement of bills inwardly and outwardly of the paper currency validator 30.

The numeral 154 denotes a second switch bracket which is secured to the cover 140; and that switch bracket supports a switch 156. The numeral 158 denotes the actuator of the switch 156; and that actuator has a convex leading edge 159 which inclines downwardly from upper left to lower right in FIG. 5. That actuator has a trailing edge 161 which is straight and which inclines downwardly from upper right to lower left in FIG. 5. The configurations and inclinations of the leading and trailing edges 159 and 161, respectively, of the switch actuator 158 enable the leading edge and trailing edge, respectively, of a bill to engage the leading edge 159 and the trailing edge 161 and easily raise that actuator upwardly out of the slot in the platen 40 which is in register with the opening 134 in the platen 140. As a result, the actuator 158 permits relatively free movement of bills inwardly and outwardly of the paper currency validator 30.

The numeral 160 denotes a third switch bracket which is secured to the cover 140; and that switch bracket is adjacent the rear of that cover. That switch bracket supports a switch 162; and that switch has an actuator 164 with a leading edge 166 and a trailing edge 168. The leading edge 166 is essentially straight, and it inclines downwardly from upper left to lower right in FIG. 5; and that leading edge will respond to the inward movement of a bill to move upwardly out of the slot 54 in the platen 40. The trailing edge 168 of the actuator 164 is generally convex in configuration, but it is quite short; and that trailing edge normally is disposed an appreciable distance below the lower face of the platen 40. As a result, the trailing edge of a bill will not normally engage the trailing edge 168 of the actuator 164 once that trailing edge has moved inwardly beyond that trailing edge of that actuator. If a person were to attempt to pull a bill outwardly of the paper currency validator 30, after the trailing edge of that bill had been moved inwardly beyond the trailing edge 168 of the actuator 164, the trailing edge of that bill would be intercepted by the inner surface of the leading edge 166 of that actuator. In that event, the actuator 164 would make it impossible for that person to recover that bill in intact form.

The numeral 170 denotes a stud-like pivot which has the reduced-diameter outer end thereof fixedly positioned within an opening in one of the flanges 142 of the cover 140. The numerals 172, 178 and 180 denote similar stud-like pivots which have the reduced-diameter outer ends thereof fixedly positioned within openings in the flanges 142. As shown by FIG. 6, the pivots 170 and 178 are in alignment with each other and are close to the front of the paper currency validator 30. The pivots 172 and 180 are in axial alignment with each other and are spaced a short distance rearwardly of the aligned pivots 170 and 178. The numeral 174 denotes a bushing which is mounted in one of the flanges 142 of the cover 140; and the numeral 176 denotes a further bushing which is mounted in the other flange 142, and that bushing is in axial alignment with the bushing 174. A shaft 182 is rotatably supported by the bushings 174 and 176; and pulleys 192 and 194, which have serrated peripheries, are fixedly secured to

that shaft. A pulley 184 is rotatably mounted on the pivot 170; and pulleys 186, 188 and 190 are rotatably mounted, respectively, on the pivots 172, 178 and 180. The pulleys 184, 186 and 192 are aligned with each other and are in register with the slot 130; and those pulleys accommodate an elongated endless belt 196 which has an outer surface that provides a high coefficient friction. The pulleys 188, 190 and 194 are aligned with each other and are in register with the slot 128; and those pulleys accommodate an elongated endless belt 198 which has an outer surface that provides a high coefficient of friction. The lower "run" of the belt 196 is engaged by the upper portions of the rollers 92, 93 and 96; and the lower run of the belt 198 is engaged by the upper portions of the rollers 82, 86 and 90.

A worm wheel 200 is fixedly secured to the shaft 182; and a worm gear 202 meshes with that worm wheel. That worm gear is mounted on the output shaft 203 of a D.C. motor 562 which is enclosed by a motor housing 204. As shown particularly by FIGS. 1 and 3, that motor housing extends upwardly from the cover 140; and it has its axis perpendicular to the central portion of that cover. The motor 562 is a reversible permanent magnet motor which drives an A.C. generator 560 by means of a connection 564. That A.C. generator is located within the motor housing 204; and the connection 564 is a direct mechanical connection. In the said preferred embodiment, the motor 562, the A.C. generator 560 and the connection 564 are parts of a type CYQM Motor With Integral Tachometer Generator which is marketed by the Barber Colman Company as Model No. CYQM 23360-3. When the motor 562 is energized in the "forward" direction, it will directly drive the A.C. generator 560, and it will drive the lower runs of the belts 196 and 198 inwardly of the paper currency validator 30. When that motor is energized in the "reverse" direction, it will directly drive the A.C. generator 560, and it will drive the lower runs of the belts 196 and 198 outwardly of that paper currency validator.

The numeral 206 denotes a mounting bracket which is shown particularly by FIG. 7; and that mounting bracket fixedly holds the magnetic heads 208 and 210 in spaced-apart relation. Slots 212 and 214 are provided in that mounting bracket; and the shank of a set screw 216 extends through the slot 212 to seat within an opening in the platen 118, while the shank of a set screw 218 extends through the slot 214 to seat within a further threaded opening in that platen. By loosening and then re-tightening the set screws 216 and 218, it is possible to adjust the longitudinal position of the mounting bracket 206 relative to the platen 118. This is desirable; because it makes it possible to position the air gaps of the magnetic heads 208 and 210 so they are precisely tangential with the upper surfaces of the rollers 102 and 114, respectively, as indicated by FIG. 5.

It will be noted that the pulleys 186 and 190 are disposed just a short distance outwardly of the magnetic head 208, as indicated by FIG. 5. This is important; because the leading edge of a well-worn, limp bill, that was being moved inwardly by the belts 196 and 198, might be unable to force the roller 102 far enough downwardly to pass between that roller and the air gap of that magnetic head. In that event, the belts 196 and 198 would continue to apply inwardly-directed forces to that bill, and would tend to wrinkle and crumple that bill up against the outer face of the magnetic head 208.

If the pulleys 186 and 190 were spaced a considerable distance outwardly of the magnetic head 208, the belts 196 and 198 might be able to move the trailing edge of such a bill well inwardly of the pulleys 186 and 190; and, thereafter when the motor 562 was reversed, the portion of the lower run of the belt 196 which is between the pulleys 186 and 192 and the portion of the lower run of the belt 198 which is between the pulleys 190 and 194 might be unable to apply sufficient pressure to the trailing edge of that bill to cause that bill to move outwardly. However, by disposing the pulleys 186 and 190 just a short distance outwardly of the magnetic head 208, the present invention enables those pulleys to hold the adjacent portions of the lower runs of the belts 196 and 198 in such intimate engagement with the rollers 93 and 86, respectively, that those portions of those belts will fully grip the trailing edge of any wrinkled or crumpled up bill. As a result, the present invention makes certain that the lower runs of the belts 196 and 198 can apply forces to the trailing edge of a wrinkled and crumpled up bill which will enable the reversal of the motor 562 to move that bill outwardly of the paper currency validator 30.

The numeral 220 denotes an elongated pivot which has the opposite ends thereof secured to the rear portions of the flanges 120 on the upper platen 118; and that pivot extends through aligned openings in the flanges 42 on the lower platen 40, as indicated by FIG. 3. Consequently, the pivot 220 enables the upper platen 118 — and the cover 140 plus the various components which are mounted on that upper platen and on that cover — to be rotated upwardly and away from the lower platen 40. Such rotation is desirable, because it permits free and ready access to the space between the lower platen 40 and the upper platen 118. However, the upper platen 118 will normally respond to its weight, to the weight of the cover 140, and to the weight of the components mounted on that upper platen and on that cover to urge the lower face of the lower run of the belt 198 into intimate engagement with the upper faces of the rollers 82, 86 and 90, and also to urge the lower face of the lower run of the belt 196 into intimate engagement with the upper faces of the rollers 92, 93 and 96. The springs 70, 72, 74, 76, 78 and the spring, not shown, which is in register with the spring 70 will yield slightly in response to the combined weights of the upper platen 118, of the cover 140, and of the components which are carried by that upper platen and by that cover; but those springs will hold the upper surfaces of the rollers 86, 82, 90, 92, 96 and 93, respectively, above the upper surface of the lower platen 40, as shown by FIG. 4.

Referring particularly to FIG. 11, the numeral 230 denotes a conductor which is connected to the positive terminal of an unregulated source of thirty volts D.C. by a conductor 232; and the numeral 234 denotes a further conductor which is connected to that positive terminal by a conductor 236. The numeral 238 denotes a conductor which serves as a ground for the sub-circuit in FIG. 11; and the numeral 240 denotes a filter capacitor which is connected between the conductor 230 and the grounded conductor 238.

Each of the magnetic heads 208 and 210 has one terminal thereof connected to the grounded conductor 238. The other terminal of the magnetic head 208 is connected to the conductor 230 by a constant current diode 242 of standard and usual design; and the other

terminal of the magnetic head 210 is connected to the conductor 234 by a similar constant current diode 244. Those constant current diodes permit a predetermined amount of direct current to flow through the coils of those magnetic heads, and thereby enable those magnetic heads to operate as biased magnetic heads.

The numeral 246 denotes an Amplifier which includes an NPN transistor 248, an NPN transistor 250, resistors 252, 254, 256 and 258, capacitors 260, 262, 264 and 266, and a diode 268. The capacitor 260 couples the output of the magnetic head 208 to the base of transistor 248; and the output of that transistor is directly coupled to the base of the transistor 250. The numeral 270 denotes an Amplifier which is shown as being identical to the Amplifier 246; and the counterpart of capacitor 260 couples the output of magnetic head 210 to the base of the counterpart of transistor 248. While the Amplifiers 246 and 270 are very useful and desirable, any suitable high quality amplifiers of comparable nature could be substituted for them.

The numeral 272 denotes a Squaring Circuit which includes an NPN transistor 274 and an inverter 276. The capacitor 266 couples the output of Amplifier 246 to the base of transistor 274; and the inverter 276 inverts the output of transistor 274 and couples it to a Frequency-Sensing Circuit 280. The numeral 278 denotes a Squaring Circuit which is identical to the Squaring Circuit 272; and the inverter in the Squaring Circuit 278 couples the output of the transistor of that Squaring Circuit to a Frequency-Sensing Circuit 292.

The Frequency-Sensing Circuit 280 includes a fixed inductor 282, fixed capacitors 284 and 286, a resistor 288, and a diode 290. The capacitors 284 and 286 coact with the inductor 282 to constitute a tuned circuit that has a center frequency of approximately 1,150 Hertz. The resistor 288 couples the output of the Squaring Circuit 272 to that tuned circuit; and the diode 290 couples the output of that tuned circuit to a Threshold Detector 294.

The Frequency-Sensing Circuit 292 is shown as being identical to the Frequency-Sensing Circuit 280; and it has a fixed inductor, two fixed capacitors a resistor, and a diode. That resistor couples the output of the Squaring Circuit 278 to the tuned circuit of the Frequency-Sensing Circuit 292; and that diode couples the output of that tuned circuit to a Threshold Detector 308.

The Threshold Detector 294 includes NPN transistors 296 and 298, a diode 300, a capacitor 302, and resistors 304 and 306. The Threshold Detector 308 includes NPN transistors 297 and 299, a diode 301, a capacitor 303, and resistors 305 and 307.

The numeral 310 denotes a Validation Latch Circuit which includes NAND gates 312 and 314, an inverter 316, and a conductor 318 which extends from the output of the inverter 316 to a conductor 319 which interconnects the lower input of NAND gate 312 and the upper input of NAND gate 314. The numeral 320 denotes a diode which has the anode thereof connected to the junction of resistors 304 and 306, and which has the cathode thereof connected to the cathode of a diode 322 and also a conductor 328. That conductor extends through FIGS. 12 and 13 and into FIG. 14. The diode 322 has the anode thereof connected to the junction of resistors 305 and 307. The numeral 326 denotes a conductor which extends from the output of inverter 316 through FIG. 12 into FIG. 13. The numeral 324 denotes a conductor which is connected to the outputs of

NAND gates 312 and 314; and that conductor extends through FIG. 12 into FIG. 13. A conductor 325 extends from the conductor 324 in FIG. 11 into FIG. 12.

Referring particularly to FIG. 12, the numeral 329 denotes a Start Switch Circuit which includes the switch 146, a resistor 330, an NPN transistor 332 and a resistor 338. The resistor 330 connects the collector of transistor 332 to the positive terminal of a regulated source of 15 volts D.C. The numeral 339 denotes a Sequence Switch Circuit which includes the switch 156, a resistor 340, an NPN transistor 342, and a resistor 346. The resistor 340 connects the collector of transistor 342 to the positive terminal of the regulated source of 15 volts D.C. The numeral 349 denotes an Exit Switch Circuit which includes the switch 162, a resistor 348, an NPN transistor 350, and a resistor 354. The resistor 348 connects the collector of transistor 350 to the positive terminal of the regulated source of 15 volts D.C.

The collector of transistor 332 is connected to the upper input of a NAND gate 334, and also to a conductor 336 which extends into FIG. 13. The collector of transistor 342 is connected to the middle input of NAND gate 334, and also to a conductor 344 which extends into FIG. 13. The collector of transistor 350 is connected to the lower input of NAND gate 334, and also to a conductor 352 which extends into FIG. 13.

The numeral 356 denotes a Vend Circuit which includes a NAND gate 358, an inverter 360, a resistor 362, an NPN transistor 364 which is connected as an 8.2 volt Zener diode, an NPN transistor 366, a relay coil 368 and a diode 370 which are connected in parallel with each other, and normally-open relay contacts 372. The lower terminal of coil 368 and the anode of diode 370 are connected to the collector of transistor 366; and the upper terminal of that coil and the cathode of that diode are connected to the positive terminal of the source of unregulated thirty volts D.C. The relay coil 368 controls the normally-open relay contacts 372; and conductors 374 and 376 extend from those relay contacts to the terminals of a vending machine, not shown. That vending machine could be a change maker, a product vendor or a vendor of services with which the paper currency validator 30 is used.

The numeral 378 denotes a conductor which extends from the output of the inverter 360 to the input of an inverter 380. The output of the latter inverter is connected to the bases of the transistors 332, 342 and 350 by the resistors 338, 346 and 354, respectively.

The numeral 382 denotes a Vent Time Circuit which includes a diode 384, a resistor 386, a capacitor 388, an NPN transistor 392 which is connected as an 8.2 volt Zener diode, resistors 394 and 396, and an NPN transistor 398. The cathode of diode 384 is directly connected to the conductor 352. The lower terminals of resistor 386 and of capacitor 388 are connected immediate the anode of diode 384 and the emitter of transistor 392; and the upper terminals of that resistor and of that capacitor are connected to the positive terminal of the source of regulated 15 volts D.C. by a conductor 390. The emitter of transistor 398 is connected to ground, the collector of that transistor is connected to conductor 325, and the base of that transistor is connected to the junction of resistors 394 and 396.

The numeral 400 denotes a Gross Time Delay Circuit which includes NPN transistors 402, 404 and 406, capacitors 408 and 410, a diode 412, and resistors 416,

418 and 420. A conductor 414 connects the collector of transistor 402 and the upper terminal of resistor 420 to the positive terminal of the source of regulated 15 volts D.C. Resistors 416 and 418 connect the emitter of transistor 402 to ground; and the junction of those resistors is connected to the base of transistor 404. The lower terminal of resistor 420 is connected to the collector of transistor 404 and to the base of transistor 406. A conductor 422 extends from the collector of transistor 406 through FIG. 13 into FIG. 14.

The numeral 424 denotes a conductor which extends from the output of NAND gate 334 to the upper terminal of capacitor 408 in the Gross Time Delay Circuit 400 and then into FIG. 13. An inverter 426 connects the output of NAND gate 334 to the lower input of NAND gate 358 in the Vent Circuit 356. The upper input of NAND gate 358 is connected to the conductor 325.

Referring particularly to FIG. 13, the numeral 428 denotes a Positional Time Delay Circuit which includes an inverter 430, diodes 432 and 434, a resistor 436, a capacitor 440, and an NPN transistor 442 which is connected as a 8.2 volt Zener diode. A conductor 438 connects the upper terminal of the resistor 436 — and hence the anodes of diodes 432 and 434, the upper terminal of capacitor 440, and the emitter of transistor 442 — to the positive terminal of the source of regulated 15 volts D.C. The cathode of diode 432 is connected to conductor 352, and the input of inverter 430 is connected to conductor 344.

The numeral 444 denotes a Further Time Delay Circuit which includes an inverter 446, diodes 448 and 450, a capacitor 452, a resistor 454, and an NPN transistor 458 which is connected as a 8.2 volt Zener diode. A conductor 456 connects the upper terminal of the resistor 454 — and hence the anodes of diodes 448 and 450, the upper terminal of capacitor 452, and the emitter of transistor 458 — to the positive terminal of the source of regulated 15 volts D.C. The cathode of diode 448 is connected to conductor 326, and the input of inverter 446 is connected to conductor 352.

The numeral 460 denotes a Time Delay Output Circuit which includes an NPN transistor 462 and a resistor 464. The collectors of the NPN transistors 442 and 458 are connected to the upper terminal of resistor 464 and to the base of transistor 462. The lower terminal of that resistor and the emitter of that transistor are grounded. The numeral 463 denotes a conductor that is connected to the collector of transistor 462; and that conductor is referred to as the motor reverse line.

The numeral 466 denotes a Motor Reverse Circuit which includes the coil 468 of a motor reverse relay that has a set of contacts 470 and a set of contacts 472 in FIG. 14. A diode 474 is connected in parallel with the relay coil 468; and the upper terminal of that relay coil and the cathode of that diode are connected to the positive terminal of the source of unregulated thirty volts D.C. The lower terminal of that relay coil and the anode of that diode are connected to the collector of an NPN transistor 476 which has the emitter thereof connected to ground by a resistor 478. A resistor 480 and a Zener diode 482 are connected as a voltage divider; and the junction between that resistor and that Zener diode is connected to the base of transistor 476. The anode of the Zener diode 482 is grounded.

The numeral 486 denotes a Tailgate Circuit which includes an inverter 488 and three diodes 490, 492 and

494. Those diodes have the anodes thereof connected together and to the input of the inverter 488. An inverter 484 connects the conductor 336 to the cathode of diode 490, and also to the upper input of a NAND gate 506 in a Bill Retrieval Circuit 504. The cathode of diode 492 is connected to conductor 344, and the cathode of diode 494 is connected to the output of inverter 446 in the Further Time Delay Circuit 444.

The numeral 496 denotes a Short Paper Circuit which includes a NAND gate 498 and diodes 500 and 502. Those diodes have the anodes thereof connected together and to the lower input of that NAND gate. The upper input of NAND gate 498 is connected to the conductor 336; and the output of that NAND gate is connected to the conductor 463. The cathode of diode 500 is connected to the output of inverter 430, and the cathode of diode 502 is connected to the conductor 352.

The middle input of the NAND gate 506 in the Bill Retrieval Circuit 504 is connected to the conductor 352; and the lower input of that NAND gate is connected to the conductor 324. The output of that NAND gate is connected to the conductor 463.

The numeral 508 denotes a Switch-Checking Circuit which includes a NAND gate 510; and the upper input of that NAND gate is connected to the conductor 336, while the lower input of that NAND gate is connected to the conductor 326. The middle input of the NAND gate 510 is connected to the output of the inverter 446 in the Further Time Delay Circuit 444, and the output of that NAND gate is connected to the conductor 463.

The numeral 512 denotes a Line Cording Circuit which includes a resistor 514 and a capacitor 516. The lower terminals of that resistor and of that capacitor are grounded, and the upper terminals of that resistor and of that capacitor are connected to the conductor 463.

The numeral 518 denotes a Reverse Relay Latch Circuit which includes inverters 520 and 522 and diodes 524 and 526. The input of inverter 520 and the anode of diode 524 are connected to the conductor 463; and the output of that inverter and the cathode of diode 526 are connected together and to the upper terminal of resistor 480 in the Motor Reverse Circuit 466. A diode 528 connects the conductor 324 and to the cathode of diode 524 and to the output of inverter 522; and a diode 532 has the cathode thereof connected to the conductor 424, and has the anode thereof connected to the input of inverter 522 and to the anode of diode 526.

The numeral 530 denotes a diode which has the cathode thereof connected to the output of inverter 488 in the Tail Gate Circuit 486. The anode of that diode is connected to the conductor 463.

Referring particularly to FIG. 14, the numeral 533 denotes an Amplitude-Responsive Control Circuit which includes an integrated circuit 534, NPN transistors 538 and 554, resistors 542, 546, 552, 556 and 558, a potentiometer 544, a capacitor 548, and a diode 550. While various integrated circuits could be used as the integrated circuit 534, the said preferred embodiment of paper currency validator uses a Motorola MC 1723-CL Voltage Regulator as that integrated circuit.

A conductor 536 connects pins 11 and 12 of the integrated circuit 534 to the positive terminal of the source of regulated fifteen volts D.C.; and pins 3 and 7 of that

integrated circuit are grounded. Pins 5 and 6 of the integrated circuit 534 are connected together; and pin 4 of that integrated circuit is connected to the movable contact of the potentiometer 544. The conductor 422 is connected to pin 13 of the integrated circuit 534, and pin 9 of that integrated circuit is connected to the base of transistor 554 by the resistor 552. Pin 2 of the integrated circuit 534 is connected to the junction of resistors 556 and 558. A conductor 540 connects the collector of transistor 538 to the positive terminal of the source of regulated 15 volts D.C. The lower terminals of resistor 558 and of capacitor 548 are grounded. The resistor 542, the potentiometer 544 and the resistor 546 are connected in series between the emitter of transistor 538 and ground.

The motor housing 204 is denoted in FIG. 14 by a dashed-line block; and that motor housing encloses the A.C. generator 560, the D.C. motor 562, and the driving connection 564. In the said preferred embodiment, a D.C. motor is selected which will produce a minimum of electrical "noise" resulting from the interaction between the brushes and the commutator thereof, because any such electrical noise would adversely affect the operation of the Frequency-Sensing Circuits 280 and 292, and could adversely affect the operation of other circuits of that preferred embodiment. However, the electrical noise from even the least noisy commercially-available, reversible, adjustable-speed D.C. motor is great enough to adversely affect the operation of the Frequency-Sensing Circuits 280 and 292; and hence a capacitor 566 is connected between the upper terminal of the motor 562 and the motor housing 204, and a capacitor 568 is connected between the upper and lower terminals of that motor. Those capacitors will effectively attenuate the electrical noise developed by the motor 562, and will thereby keep that electrical noise from affecting the operation of any other component or sub-circuit of the paper currency validator 30.

The upper terminal of the motor 562 is connected to the left-hand stationary relay contact 470, and also to the stationary right-hand relay contact 472. The lower terminal of that motor is connected to the left-hand stationary relay contact 472, and also to the stationary right-hand relay contact 470. The movable relay contact 470 is connected to the positive terminal of the source of unregulated 30 volts D.C. by a conductor 569. The movable relay contact 472 is connected to the collector of the transistor 554; and a diode 570 has the anode thereof connected to the movable relay contact 472, and has the cathode thereof connected to the movable relay contact 470. That diode will provide a discharge path for the inductive energy within the motor 562 whenever the current flowing through that motor is interrupted.

The numeral 572 denotes a Current-Sensing Circuit which includes a differential amplifier 574, a potentiometer 580, resistors 578 and 582, and an inverter 586. One terminal of that differential amplifier is connected to ground, and another terminal of that differential amplifier is connected to the positive terminal of the source of regulated 15 volts D.C. by a conductor 576. The resistor 578, the potentiometer 580, and the resistor 582 are connected between ground and a conductor 584 which extends to the positive terminal of the source of regulated 15 volts D.C.

The movable contact of the potentiometer 580 is connected to the lower input terminal of the differential amplifier 574; and the emitter of that transistor 554 is connected to the upper input terminal of that differential amplifier. The input of the inverter 586 is connected to the output of the differential amplifier 574; and the output of that inverter is connected to the conductor 328.

Referring particularly to FIG. 15, the numeral 588 denotes a Frequency-Responsive Control Circuit which can be substituted for the Amplitude-Responsive Control Circuit 533 of FIG. 14. That Frequency-Responsive Control Circuit is not, per se, a part of the present invention; and it is disclosed herein solely to illustrate the adaptability of the circuitry of FIGS. 11-13 to various speed-regulating control systems. That Frequency-Responsive Control Circuit includes NPN transistors 590, 624, 630 and 670, resistors 592, 594, 602, 614, 622, 626, 632, 634, 636, 638, 644, 648, 664, 666, 668, 672 and 674, diodes 598 and 656, a stable, non-retriggering one-shot 606, a potentiometer 646, capacitors 600, 608, 610, 616, 640, 642, 658 and 660, an inverter 620, and an operational amplifier 650. A conductor 596 connects the upper terminal of resistor 594 to the positive terminal of the source of regulated 15 volts D.C., and the left-hand terminal of resistor 592 is connected to the un-grounded output terminal of the A.C. generator 560. The diode 598 has the anode thereof grounded, and has the cathode thereof connected between resistor 592 and the base of transistor 590. The emitter of transistor 590 is grounded, and the collector of that transistor is connected to the lower terminal of resistor 594.

The resistor 602 has the lower terminal thereof connected between the capacitor 600 and pin 2 of the one-shot 606; and the upper terminal of that resistor is connected to the positive terminal of the source of regulated 15 volts D.C. by a conductor 604. That capacitor and that resistor constitute a differentiator; and the output of that differentiator is applied to pin 2 of the one-shot 606. That one-shot will change the state of the output at pin 3 thereof only when a negative-going signal is applied to the pin 2.

The capacitor 608 connects pin 4 of the one-shot 606 to ground, and the capacitor 610 connects pin 5 of that one-shot to ground. A conductor 612 connects pin 8 of the one-shot 606 to the positive terminal of the source of regulated 15 volts D.C.; and the resistor 614 has the upper terminal thereof connected to that positive terminal by a conductor 618. The capacitor 616 connects the lower terminal of resistor 614 to ground; and the junction between that resistor and that capacitor is connected to pins 6 and 7 of the one-shot 606.

The inverter 620 has the input thereof connected to the conductor 422, and has the output thereof connected to the base of transistor 624 by the resistor 622. The resistor 626 has the upper terminal thereof connected to the positive terminal of the source of regulated 15 volts D.C. by a conductor 628; and the lower terminal of that resistor is connected to the collector of transistor 624, to the collector of transistor 630, to the upper terminal of resistor 634, and to the left-hand terminal of resistor 636. The emitter of transistor 630 is grounded, and the base of that transistor is connected to the pin 3 of the one-shot 606 by the resistor 632. The right-hand terminal of resistor 636 is connected to the upper terminal of resistor 638, to the upper terminal of

capacitor 642, and to the upper input of operational amplifier 650. The lower terminal of resistor 638 is connected to ground by the capacitor 640.

Resistor 644 has the upper terminal thereof connected to the positive terminal of the source of regulated 15 volts D.C.; and the lower terminal of that resistor is connected to the upper terminal of potentiometer 646 which has the lower terminal thereof connected to ground by resistor 648. Resistor 664 connects the movable contact of potentiometer 646 to the lower input of operational amplifier 650; and one terminal of that operational amplifier is connected to the positive terminal of the source of regulated 15 volts D.C. by a conductor 652, while another terminal of that operational amplifier is connected to the negative terminal of that source of regulated 15 volts D.C. by a conductor 654. The upper terminals of resistor 638 and of capacitor 642 are connected to the upper input of operational amplifier 650. The diode 656 has the anode thereof connected to the output of operational amplifier 650, and has the cathode thereof connected to the base of transistor 670 by the resistor 666. The capacitor 658 and the series-connected capacitor 660 and resistor 662 constitute feed back paths from the cathode of diode 656 to the lower input of operational amplifier 650. The resistor 668 is connected between ground and the right-hand terminal of resistor 666 and the base of transistor 670; and resistors 672 and 674 are connected in series between the emitter of that transistor and ground. That emitter is connected to the upper input of the differential amplifier 574 of a Current-Sensing Circuit 572 which is identical to the similarly-numbered Current-Sensing Circuit of FIG. 14. The collector of transistor 670 is connected to movable relay contact 472 and to the anode of diode 570; and that movable relay contact, that diode, the other relay contacts 472, the relay contacts 470, the motor 562, the motor housing 204, the A.C. generator 560, the connection 564, the capacitors 566 and 568, and the conductor 569 of FIG. 15 are identical to the similarly-numbered elements in FIG. 14. Effectively, the sub-circuit of FIG. 15 is the same as the sub-circuit of FIG. 14 except for the substitution of the Frequency-Responsive Control Circuit 588 for the Amplitude-Responsive Control Circuit 533 of FIG. 14.

The values of capacitors 658 and 660 and the value of resistor 662 are selected to make the sub-circuit of FIG. 15 operate as a second order system. Such a system is a slightly underdamped system; and hence it will permit a very small amount of overshooting to occur — thereby enabling that sub-circuit to provide a desirably rapid response.

In the said preferred embodiment, some of the NAND gates are portions of integrated circuits, and some of the inverters are parts of integrated circuits. For example, the NAND gates 312 and 314 of FIG. 11, the NAND gate 358 in FIG. 12, and the NAND gate 498 in FIG. 13 are parts of a quad 2-input NAND gate which is identified as Motorola MC 668. The NAND gate 334 in FIG. 12 and the NAND gates 506 and 510 in FIG. 13 are parts of a three 3-input NAND gate which is identified as Motorola MC 670. The inverter 276 and its counterpart in FIG. 11, and the inverters 430, 446, 484 and 488 in FIG. 13 are parts of a hex inverter which is identified as Motorola MC 680; and the inverter 316 in FIG. 11, the inverters 360, 380 and 426 in FIG. 12, and the inverters 520 and 522 in FIG. 13 are

parts of another hex inverter which is identified as Motorola MC 680.

The differential amplifier 574 in FIGS. 14 and 15 can be an operational amplifier which is identified as Motorola MC 1741-CP 1. The one-shot 606 in FIG. 15 can be a timer which is identified as Signetics NE 555V. The operational amplifier 650 in FIG. 15 can be an operational amplifier which is identified as Motorola MC 1741-CP 1. The other components of FIGS. 11-15 can be standard and usual commercial grade components.

In the said preferred embodiment, the length of the lower platen 40 is shorter than the length of a U.S. dollar bill. Specifically, the distance from the rear edge of the upwardly-inclined inner end 38 of the platform 32 to the rear of the downwardly-inclined trailing edge 45 of the lower platen 40 is about 5-7/16 inches, whereas the average length of a U.S. dollar bill is about 6-1/8 inches. The upper platen 118 is slightly longer than the lower platen 40, as indicated by FIGS. 4 and 5; and the distance from a vertical projection of the front of the semi-cylindrical leading edge 124 to a vertical projection of the rear of the trailing edge 126 is just slightly less than 6 inches. Consequently, the upper platen 118 also is shorter than a U.S. dollar bill. The distance between the downwardly-directed flanges 120 at the sides of the upper platen 118 is slightly greater than the width of a U.S. dollar bill; and hence such a bill can easily be moved inwardly of the space defined by the lower platen 40, the upper platen 118, and the flanges 120 on that upper platen.

The outer end of the slot 52 in the lower platen 40 is located about eleven-sixteenths of an inch inwardly of the rear edge of the upwardly-inclined inner end of the platform 32; and the outer end of the slot, not shown, in that platen, which is in register with the slot 134 in the platen 118, is located about fifteen-sixteenths of an inch inwardly of that rear edge of that upwardly-inclined inner end. Each of those slots is approximately 1 1/8 of an inch long and approximately one-eighth of an inch wide. The outer end of the slot 54 in the platen 40 is located about 1 1/4 inches outwardly of the rear of the downwardly-inclined trailing edge 45 of that platen; and that slot is approximately fifteen-sixteenths of an inch long and approximately five-sixteenths of an inch wide.

The outer end of each of the slots 46 and 56 in the platen 40 is located about 1 inch inwardly of the rear edge of the upwardly-inclined inner end 38 of the platform 32; and each of those slots is about one-half of an inch long and about nine thirty-seconds of an inch wide. The distance between the inner edge of slot 46 and the outer edge of the slot 48 is about one-half of an inch; and, similarly, the distance between the confronting edges of the slots 56 and 58 is about one-half of an inch. Each of the slots 48 and 58 is about one-half of an inch long and about nine thirty-seconds of an inch wide. The distance between the confronting edges of the slots 48 and 50 is about 2-1/32 of an inch; and, similarly, the distance between the confronting edges of the slots 58 and 60 is about 2-1/32 of an inch. The outer edge of the slot, not shown, which receives the roller 102 is located about 2 1/2 inches inwardly of the rear edge of the upwardly-inclined inner end 38 of the platform 32; and the outer edge of the slot, not shown, which accommodates the roller 114 is located about

seven-sixteenths of an inch inwardly of the inner edge of the slot which accommodates the roller 102.

The switch actuator 148 is located so the leading edge of a bill must be moved about 1-5/16 of an inch inwardly of a vertical projection of the front of the semi-cylindrical leading edge 124 of platen 118 before it moves that switch actuator far enough to close switch 146. The leading edge of that bill must be moved about three-eighths of an inch further inwardly before it can engage the lower runs of belts 196 and 198. After the leading edge of that bill has been moved inwardly of the vertical projection of the front of the semi-circular leading edge 124 of platen 118 a total distance of about 1-13/16 of an inch, that leading edge will cause the switch actuator 158 to close the switch 156. Not until the leading edge of the bill has been moved a total distance of approximately 4-15/16 of an inch inwardly of the vertical projection of the front of the semi-cylindrical leading edge 124 of the upper platen 118 will that leading edge cause the switch actuator 164 to close the switch 162.

The air gap of the magnetic head 208 is located about 3-3/16 of an inch inwardly of the front of the semi-cylindrical leading edge 124 of the upper platen 118; and the air gap of the magnetic head 210 is located about 1 inch further inwardly. The leading edge of the ovate portrait background on a U.S. dollar bill will not move into register with the air gap of the magnetic head 208 until the leading edge of that bill has caused the switch actuator 164 to close the switch 162, and then has been moved approximately three-quarters of an inch further inwardly.

The leading edge of the inserted bill must be moved approximately 4-3/16 of an inch, after it has caused the actuator 158 to close the switch 156, before that leading edge can cause the actuator 164 to close the switch 162. Furthermore, the bill must be moved approximately 1 1/4 of an inch further inwardly of the paper currency validator 30, after the leading edge of that bill has caused the actuator 164 to close the switch 162, before the vertical grid lines in the leading half of the portrait background can engage the air gap of the magnetic head 210 and the vertical grid lines in the trailing half of that portrait background can engage the air gap of the magnetic head 208.

The motor 562 will drive the pulleys 192 and 194 by means of its output shaft 203, worm gear 202, worm wheel 200, and the shaft 182. That motor will drive the pulleys 192 and 194 at a speed which will make the linear speed of each of the belts between 9-1/10 and 9-5/10 of an inch per second. Those belts will cause an inserted bill to move at that same speed; and hence that bill will move inwardly at a rate between 9-1/10 and 9-5/10 of an inch per second. This means that it will take an inserted bill approximately 450 milliseconds to move from the position wherein it effects closure of the switch 156 to the position wherein it effects closure of the switch 162. Thereafter, it will take that bill approximately 188 milliseconds to move from the position wherein it effects closure of the switch 162 to the position wherein the air gaps of both magnetic heads 208 and 210 should sense vertical grid lines in the portrait background. Those vertical grid lines will move past those air gaps at a rate of approximately 1150 times a second.

Whenever the paper currency validator 30 is in its standby condition, the switches 146, 156 and 162 will

be open, as shown by FIG. 12. As a result, all of the transistors 332, 342, 350 will be non-conductive; and essentially 15 volts will appear at the collectors of each of those transistors. That voltage will constitute a logic "1" whereas ground voltage will constitute a logic "0". This means that in the standby condition of the paper currency validator 30, logic 1 will appear at all of the inputs of the NAND gate 334, at the input of inverter 484 in FIG. 13, at the upper input of NAND gate 498 in FIG. 13, and at the upper input of NAND gate 510 in FIG. 13. Additionally, logic 1 will appear at the input of inverter 430 in FIG. 13 and at the cathode of diode 492 in FIG. 13. Further, logic 1 will appear at the cathode of diode 384 in FIG. 12, at the cathode of diode 432 in FIG. 13, at the input of inverter 446 in FIG. 13, at the cathode of diode 502 in FIG. 13, and at the middle input of NAND gate 506 in FIG. 13. The output of NAND gate 334 in FIG. 12 will be logic 0; and hence the transistor 402 in the Gross Time Delay Circuit 400 of FIG. 12 will be non-conductive and the transistor 404 in that circuit also will be non-conductive. However, transistor 406 in that circuit will be conductive; and hence the conductor 422 will apply logic 0 to the pin 13 of the voltage regulator 534 in FIG. 14 — thereby causing pin 9 of that voltage regulator to apply logic 0 to the base of transistor 554. This means that the motor 562 will be de-energized, and the belts 196 and 198 will be stationary. At this time, logic 0 will appear at pin 2 of the voltage regulator 534; and logic 0 will appear at the movable contact of potentiometer 544 — and hence at pin 4 of that voltage regulator.

The magnetic heads 208 and 210 will have D.C. biasing currents flowing through them; but those magnetic heads will not supply any signals, to the capacitor 260 in the Amplifier 246 or to the counterpart capacitor in the Amplifier 270, which could be amplified by those Amplifiers. As a result, the transistors 296 and 297 in the Threshold Detectors 294 and 308 will be non-conductive; and hence the collector of transistor 298 will apply logic 1 to the upper input of NAND gate 312, while the collector of transistor 299 will apply logic 1 to the lower input of NAND gate 314. If, at the time the paper currency validator 30 was connected to the sources of regulated 15 volts D.C. and of unregulated 30 volts D.C., the voltage at the lower input of NAND gate 312 had been logic 0, logic 1 would have appeared at the output of that NAND gate; and that logic 1 would have been applied by the conductors 324 and 325 to the collector of transistor 398 in FIG. 12. Because the diode 384 would have had logic 1 at the cathode thereof, that diode would have been back-biased; and hence parallel connected resistor 386 and capacitor 388, transistor 392, and resistors 394 and 396 would have applied a positive voltage to the base of transistor 398 which would have rendered that transistor conductive. Thereupon, that transistor would have provided a logic 0 on the conductors 325 and 324, and thus at the input of inverter 316; and that inverter would have applied logic 1 to the lower input of NAND gate 312 and to the upper input of NAND gate 314. Those NAND gates would then have provided logic 0 on conductors 324 and 325 and at the input of inverter 316; and that inverter would thereafter have maintained logic 1 at the lower input of NAND gate 312, at the upper input of NAND gate 314, at the cathode of diode 448 in FIG. 13, and at the lower input of NAND gate 510 in FIG. 13. The logic 0 on the conductor 324

would have back-biased the diode 528 and would have appeared at the lower input of NAND gate 506; and the logic 0 on the conductor 325 would have rendered the transistor 398 non-conductive. The conductor 325 is considered to be the validation line of the paper currency validator 30; and the logic 0 on that conductor during the standby condition of that paper currency validator means that no validation signal is present during that standby condition.

The logic 0 on the conductor 325 will be applied to the upper input of NAND gate 358; and the resulting logic 1 at the output of that NAND gate will cause the inverter 360 to apply logic 0 to the base of transistor 366 and to the input of inverter 380. Transistor 366 will respond to the logic 0 at the base thereof to be non-conductive; and hence the vend relay coil 368 will be de-energized and will leave the relay contacts 372 open. This means that the Vend Circuit 356 will not be supplying a vend signal during the standby condition of the paper currency validator 30.

The logic 0 at the input of inverter 380 will cause that inverter to apply logic 1 to the base of each of the transistors 332, 342 and 350 in FIG. 12. However, all of those transistors will be non-conductive, because the emitters thereof are disconnected from ground by the open switches 146, 156 and 162.

The inverter 430 in FIG. 13 will respond to the logic 1 at the input thereof to apply logic 0 to the cathode of diode 434 and to the cathode of diode 500. The diode 434 will thus be forward-biased; and it will apply logic 0 to the upper terminal of capacitor 440 and to the emitter of transistor 442, thereby keeping that transistor from applying a positive voltage to the base of transistor 462. The inverter 446 in FIG. 13 will respond to the logic 1 at the input thereof to apply logic 0 to the cathode of diode 450, to the cathode of diode 494, and to the middle input of NAND gate 510. The diode 450 will thus be forward-biased; and it will apply logic 0 to the upper terminal of capacitor 452 and to the emitter of transistor 458, thereby keeping that transistor from applying a positive voltage to the base of transistor 462. As a result, the transistor 462 in the Time Delay Output Circuit 460 will be non-conductive; and it will tend to provide logic 1 on conductor 463. This means that logic 1 will appear on the motor reverse line 463 during the standby condition of paper currency validator 30.

The logic 1 at the cathode of diode 432 will back-bias that diode; but the forward-biased diode 434 will keep logic 0 on the upper terminal of capacitor 440 and at the emitter of transistor 442. Similarly, the logic 1 at the cathode of diode 448 will back-bias that diode; but the forward-biased diode 450 will keep logic 0 on the upper terminal of capacitor 452 and at the emitter of transistor 458. Consequently, as indicated hereinbefore, the transistor 462 will be non-conductive and will provide logic 1 on the conductor 463.

The inverter 484 in FIG. 13 will respond to the logic 1 at the input thereof to apply logic 0 to the cathode of diode 490 and also to the upper input of NAND gate 506. The logic 1 at the cathode of diode 492 in FIG. 13 will back-bias that diode; but the logic 0 at the cathodes of the diodes 490 and 494 will forward-bias those diodes — thus causing those diodes to apply logic 0 to the input of inverter 488. The resulting logic 1 at the output of that inverter will back-bias the diode 530 —

thereby permitting logic 1 to remain on the conductor 463.

The logic 1 on the cathode of diode 502 will back-bias that diode; but the logic 0 on the cathode of diode 500 will forward-bias that diode — thus causing that diode to apply logic 0 to the lower input of NAND gate 498. Although logic 1 is applied to the upper input of that NAND gate, that NAND gate will respond to the logic 0 at the lower input thereof to permit logic 1 to remain on the conductor 463.

The logic 1 on the middle input of the NAND gate 506 will tend to develop a logic 0 at the output of that NAND gate; but logic 0 appears at both the upper and lower inputs of that NAND gate. As a result, that NAND gate will permit logic 1 to remain on the conductor 463.

The logic 1 on the upper and lower inputs of the NAND gate 510 will tend to develop a logic 0 at the output of that NAND gate; but logic 0 appears at the middle input of that NAND gate. As a result, that NAND gate will permit logic 1 to remain on the conductor 463.

The logic 1 on the conductor 463 will cause the inverter 520 to apply logic 0 to the cathode of diode 526 and also to the base of transistor 476. That transistor will respond to that logic 0 to remain non-conductive; and hence the relay coil 468 will remain de-energized. This means that the relay contacts 470 and 472 will be in the "forward" position shown by FIG. 14. The logic 0 at the cathode of diode 532 in FIG. 13 will forward-bias that diode; and that diode will apply logic 0 to the anode of diode 526 and to the input of inverter 522. The diode 526 will be back-biased; and the inverter 522 will apply logic 1 to the cathodes of diodes 524 and 528 to back-bias those diodes.

The capacitor 516 in the Line Cording Circuit 512 will have logic 1 applied to the upper terminal thereof; and hence that capacitor will be charged. The standby voltage across that capacitor will be about 12 volts.

The movable contact of potentiometer 580 in FIG. 14 will apply a positive voltage to the lower input of the differential amplifier 574. However, the emitter of transistor 554 will apply zero voltage to the upper input of that differential amplifier; and hence that differential amplifier will provide logic 0 at the output thereof. The inverter 586 will respond to that logic 0 to apply logic 1 to the cathodes of diodes 320 and 322 in FIG. 11.

The overall result is that whenever the paper currency validator 30 is in its standby condition, logic 0 appears on the validation conductor 325, logic 1 appears on the motor reverse conductor 463, the relay contacts 470 and 472 are in the forward position of FIG. 14, the motor 562 is de-energized, and the vend relay contacts 372 are open. Each of the transistors 332, 342 and 350 has positive voltages at the collector and base thereof, but all of those transistors are non-conductive because the switches 146, 156 and 162 are open. However, as soon as any of those switches is closed, the transistor which has the emitter thereof connected to that switch will become conductive.

The Gross Time Delay Circuit 400 in FIG. 12 acts as an inexpensive and simple switch and timer. Specifically, as long as the paper currency validator 30 is in its standby condition, the transistor 402 of that Gross Time Delay Circuit will respond to the logic 0 at the upper terminal of capacitor 408 to remain non-conductive, and will thereby apply logic 0 to the base

of transistor 404. The latter transistor will remain non-conductive, and will thereby apply logic 1 to the base of transistor 406 — to cause that transistor to be conductive and to apply logic 0 to the conductor 422. However, as soon as any of the switches 146, 156 and 162 is closed, the resulting logic 1 at the upper terminal of capacitor 408 will cause current to flow through that capacitor and through parallel-connected capacitor 410 and the base-emitter circuit of transistor 402 — to render that transistor conductive. The consequent flow of current through transistor 402, resistor 416, and parallel-connected resistor 418 and the base-emitter circuit of transistor 404 will render the latter transistor conductive — to effectively shunt the base-emitter circuit of transistor 406, and thereby render that transistor non-conductive. At this time, the Gross Time Delay Circuit 400 will change the logic 0 on the conductor 422 to logic 1.

The capacitors 408 and 410 will continue to charge; and, at the conclusion of a time interval which will vary between 6 and 12 seconds with variations in the manufacturing tolerances of those capacitors and of transistor 402, those capacitors will have become charged to such an extent that the flow of current through capacitor 408 and the base-emitter circuit of transistor 402 will be too small to keep that transistor conductive. Thereupon, that transistor will become non-conductive to render transistor 404 non-conductive — thereby enabling transistor 406 to again become conductive to change the logic 1 on conductor 422 back to logic 0. This means that if any or all of the switches 146, 156 and 162 closes for a given time interval of from six to twelve seconds, the Gross Time Delay Circuit 400 will initially change the logic 0 on conductor 422 to logic 1 and will then — at the end of that time interval — change the logic 1 on that conductor back to logic 0.

During normal operation of the paper currency validator 30, none of the switches 146, 156 and 162 will remain closed for a given time interval of from 6 to 12 seconds and, instead, will re-open to less than a second after it was closed. Hence, during normal operation of that paper currency validator, the capacitors 408 and 410 will not have time to become substantially-fully charged to render transistor 402 non-conductive. As a result, during normal operation of the paper currency validator 30, the logic 0 at the upper terminal of capacitor 408 will be restored before the transistor 402 can become non-conductive; and hence, during such normal operation, the Gross Time Delay Circuit 400 will respond to the closing of any of the switches 146, 156 and 162 to change the logic 0 on conductor 422 to logic "1", and then will hold that logic 1 on that conductor as long as any of those switches remains closed. However if, for any reason, any of those switches remains closed for a time interval between 6 and 12 seconds, the Gross Time Delay Circuit 400 will automatically change the logic 1 on conductor 422 back to logic 0.

It thus should be apparent that the Gross Time Delay Circuit 400 is both a switch and a timer. Although the duration of the time interval during which that Gross Time Delay Circuit can hold logic 1 on conductor 422 is not precise, a precise time interval is not required; because the restoration of logic 0 on the conductor 422 is merely needed to prevent continuous operation of

the motor 562 in the event one of the switches 146, 156 and 162 does not re-open.

The Vend Time Circuit 382 in FIG. 12 is a timing circuit which provides a time delay of about 150 milliseconds. During the standby condition of the paper currency validator 30, the diode 384 of that Vend Time Circuit is back-biased by the logic 1 on conductor 352; and conductor 390, resistor 386, transistor 392, and resistors 394 and 396 permit sufficient current to flow through the resistor 396 to forward-bias the base-emitter circuit of transistor 398. However, because the sub-circuit of FIG. 11 is maintaining logic 0 on conductor 325, that transistor will be non-conductive.

As soon as the switch 162 is closed, the diode 384 in the Vend Time Circuit 382 will be forward-biased; and it will start discharging the capacitor 388 via transistor 350 and switch 162 to ground. After about one half of a millisecond, the voltage at the emitter of transistor 392 will fall below the Zener voltage of that transistor; and, thereupon, the voltage at the base of transistor 398 will fall to zero, and that transistor will no longer be forward-biased. The capacitor 388 will continue to discharge via transistor 350 and switch 162 until it is fully discharged.

The Vend Time Circuit 382 will continue to leave zero voltage on the base of transistor 398 as long as the switch 162 remains closed; but, when that switch re-opens, the capacitor 388 will begin to charge. That capacitor and resistor 386 constitute an RC circuit which will permit the voltage at the emitter of transistor 392 to remain below the Zener voltage of that transistor for a time interval of about 150 milliseconds. At the end of that time interval, the base-emitter circuit of transistor 398 will again be forward-biased; and, if the sub-circuit of FIG. 11 has previously changed the logic 0 on conductor 325 to logic 1, that transistor will become conductive and will apply logic 0 to the conductor 325. This means that the Vend Time Circuit 382 will forward-bias the base-emitter circuit of transistor 398 until the switch 162 is closed, will remove the forward-bias on that base-emitter circuit as long as that switch remains closed, and subsequently will again forward-bias that base-emitter circuit about 150 milliseconds after that switch re-opens.

The Positional Time Delay Circuit 428 in FIG. 13 is a timing circuit which provides a time delay of about 550 milliseconds. During the standby condition of the paper currency validator 30, the diode 432 is back-biased by the logic 1 at the cathode thereof, but the diode 434 is forward-biased by the logic 0 which the inverter 430 applies to the cathode thereof. Because the latter diode is forward-biased, it connects the upper terminal of capacitor 440 to ground via the output of inverter 430 — thereby keeping that capacitor discharged to maintain the voltage at the emitter of transistor 442 below the Zener voltage of that transistor. The resulting logic 0 at the collector of that transistor will keep the transistor 462 non-conductive, and will thereby enable logic 1 to remain on conductor 463.

However, when the switch 156 is closed, the resulting logic 0 at the input of inverter 430 will cause that inverter to back-bias the diode 434; and, thereupon, current will flow from conductor 438 via resistor 436 and capacitor 440 to start charging that capacitor. That resistor and that capacitor constitute an RC circuit which will keep the voltage at the upper terminal of that capacitor, and thus at the emitter of transistor 442,

from reaching the Zener voltage of that transistor for a time interval of about 550 milliseconds after the switch 156 is closed.

If the switch 162 is closed before the end of that time interval — as will be the case during normal operation of the paper currency validator 30 — the resulting logic 0 at the cathode of diode 432 will forward-bias that diode, and will thereby discharge capacitor 440 via that diode, conductor 352, transistor 350, and switch 162 to ground. Consequently, even though switch 156 and inverter 430 continue to back-bias the diode 434, the capacitor 440 will become discharged; and hence the voltage at the emitter of transistor 442 will not be able to reach the Zener voltage of that transistor. If, however, the switch 162 is not closed before the end of the 550 milliseconds time interval, the voltage at the emitter of transistor 442 will reach the Zener voltage of that transistor, and will thereby render the transistor 462 conductive. All of this means that if the switch 162 is closed with 550 milliseconds after the switch 156 is closed, logic 1 can continue to appear on the conductor 463. However, if the switch 162 is not closed within 550 milliseconds after the switch 156 is closed, logic 0 will automatically appear on that conductor.

The Further Time Delay Circuit 444 in FIG. 13 is a timing circuit which provides a time interval between 250 and 300 milliseconds. During the standby condition of the paper currency validator 30, the diode 448 of that Further Time Delay Circuit is back-biased by the logic 1 on conductor 326, but the diode 450 is forward-biased by the logic 0 which the inverter 446 applies to the cathode thereof. Because the latter diode is forward-biased, it connects the upper terminal of capacitor 452 to ground via the output of inverter 446 — thereby keeping that capacitor discharged to maintain the voltage at the emitter of transistor 458 below the Zener voltage of that transistor. The resulting logic 0 at the collector of that transistor will keep the transistor 462 non-conductive, and will thereby enable logic 1 to remain on conductor 463.

However, when the switch 162 is closed, the resulting logic 0 at the input of inverter 446 will cause that inverter to back-bias the diode 450; and, thereupon, current will flow from conductor 456 via resistor 454 and capacitor 452 to start charging that capacitor. That resistor and that capacitor constitute an RC circuit which will keep the voltage at the upper terminal of that capacitor, and thus at the emitter of transistor 458, from reaching the Zener voltage of that transistor for a time interval between 250 and 300 milliseconds after the switch 162 is closed.

If the inverter 316 in the sub-circuit of FIG. 11 changes the logic 1 on conductor 326 to logic 0 before the end of that time interval — as will be the case during normal operation of the paper currency validator 30 — the resulting logic 0 at the cathode of diode 448 will forward-bias that diode, and will thereby discharge capacitor 452 via that diode, conductor 326 and that inverter to ground. Consequently, even though switch 162 and inverter 446 continue to back-bias the diode 450, the capacitor 452 will become discharged; and hence the voltage at the emitter of transistor 458 will not be able to reach the Zener voltage of that transistor. If, however, the inverter 316 in the sub-circuit of FIG. 11 does not change the logic 1 on conductor 326 to logic 0 before the end of the 250 to 300 millisecond time interval, the voltage at the emitter of transistor

458 will reach the Zener voltage of that transistor, and will thereby render the transistor 462 conductive. All of this means that if the inverter 316 in the sub-circuit of FIG. 11 changes the logic 1 on conductor 326 to logic 0 before the end of the 250 to 300 millisecond time interval, logic 1 can continue to appear on the conductor 463. However, if that inverter does not change the logic 1 on conductor 326 to logic 0 before the end of that time interval, 0 will automatically appear on that conductor.

When the leading edge of the green-ink face of an authentic U.S. one dollar bill is placed on the platform 32 and is then moved inwardly into the space defined by the lower and upper platens 40 and 118, respectively, the leading edge of that bill will engage the leading edge 150 of the actuator 148 and will thereby raise that actuator to close the switch 146. Thereupon, the emitter of transistor 332 will be connected to ground; and that transistor will become conductive. The collector of that transistor will apply logic "zero" to the upper input of NAND gate 334 and also to the input of inverter 484, to the upper input of NAND gate 498, and to the upper input of NAND gate 510 in FIG. 13. The inverter 484 will apply logic 1 to the cathode of diode 490 and to the upper input of NAND gate 506; but the signal at the input of inverter 488 will remain logic 0, because diode 494 will still be forward-biased; and hence that inverter will back-bias the diode 530. The logic 0 at the upper input of the NAND gate 498 will leave the output of that NAND gate logic 1, and the logic 0 at the upper input of the NAND gate 510 will leave the output of that NAND gate logic 1. The logic 1 at the upper input of NAND gate 506 will not change the output of that NAND gate because conductor 324 applies logic 0 to the lower input of that NAND gate. This means that logic 1 will remain on the motor reverse line 463; and hence the motor reverse relay coil 468 will remain de-energized, and the relay contacts 470 and 472 will remain in the "forward" position of FIG. 14.

The output of NAND gate 334 will become logic 1, and the inverter 426 will respond to that logic 1 to apply logic 0 to the lower input of NAND 358; and that logic 0 and the logic 0 at the upper and lower inputs of that NAND gate will keep the output of that NAND gate at logic 1. As a result, the transistor 366 will continue to be non-conductive; and the inverter 380 will continue to apply logic 1 to the bases of transistors 332, 342 and 350.

The logic 1 at the output of NAND gate 334 will initiate the time delay of between 6 and 12 seconds which is provided by the Gross Time Delay Circuit 400, all as explained hereinbefore; and, during that time delay, the transistor 406 of that Gross Time Delay Circuit will develop and maintain logic 1 on the conductor 422. The resulting application of logic 1 to pin 13 of voltage regulator 534 in FIG. 14 will cause that voltage regulator to develop a positive voltage of about 15 volts at the pin 9 thereof, and hence at the base of transistor 554. Thereupon, that transistor will become conductive at the saturation level, and will permit substantial current to flow from conductor 569 via the movable and left-hand relay contacts 470, motor 562, the left-hand and movable relay contacts 472, transistor 554, and resistors 556 and 558 to ground. As a result, the motor 562 will start operating in the forward direction; and the lower runs of the belts 196 and 198 will grip the leading

edge of the bill as that leading edge is pushed into engagement with those runs.

As the motor 562 operates in the forward direction, the A.C. generator 560 will develop a feed back signal which will be rectified by the diode 550 and filtered by the capacitor 548 and then applied to the base of transistor 538. That rectified and filtered signal will render the transistor 538 conductive, and thus will cause a voltage to develop at the movable contact of the potentiometer 544. That rectified and filtered signal will be a function of the speed of the motor 562, and hence the degree of conductivity of transistor 538 and the voltage at the movable contact of potentiometer 544, will be a function of the speed of that motor.

15 The voltage regulator 534 maintains a regulated positive 5-6/10 volts at the pin 6 thereof; and that voltage is directly applied to the pin 5 — which is the inverting input of a differential amplifier within the voltage regulator 534. The pin 4 is the non-inverting input of that differential amplifier; and that differential amplifier will act, whenever the voltage at the pin 4 is below 5-6/10 volts, to apply an error signal to the base of transistor 554 which will cause that transistor to supply enough current to the motor 562 to enable that motor 20 to increase its speed. Consequently, that motor will quickly reach its intended speed — which is determined by the setting of the movable contact of the potentiometer 544.

25 The output shaft of the motor 562 will drive the worm gear 202 in a direction which will enable the worm wheel 200, the shaft 182 and the pulleys 192 and 194 to cause the lower runs of the belts 196 and 198 to move inwardly of the paper currency validator 30 at a speed of between 9-1/10 and 9-5/10 of an inch per second. After the leading edge of the bill has been gripped by those lower runs and has started moving inwardly of the paper currency validator 30; that leading edge will quickly be moved into engagement with the leading edge 159 of actuator 158 to raise that actuator 30 and thereby close the switch 156. Thereupon, the emitter of transistor 342 will be connected to ground; and that transistor will become conductive and will apply logic 0 to the middle input of NAND gate 334 and to the input of inverter 430 and to the cathode of diode 492 in FIG. 13. The logic 0 at the middle input of NAND gate 334 will not change the output of that NAND gate, because that output became logic 1 when transistor 332 became conductive. Also the logic 0 at the cathode of diode 492 will not change the voltage at the input of inverter 488 in FIG. 13, because diode 494 will still be forward-biased by the logic 0 at the output of inverter 446. However, the application of logic 0 to the input of inverter 430 will make the output of that inverter logic 1, and thus will back-bias diode 434 and diode 500 in FIG. 13. The back-biasing of diode 500 will not be significant at this time; because the logic 0 which the closing of switch 146 applied, and continues to apply, to the upper input of NAND gate 498 will continue to cause that NAND gate to develop logic 1 at the output thereof. The back-biasing of diode 434 will, however, be significant because it will initiate the 550 millisecond time delay provided by the Positional Time Delay Circuit 428, all as explained hereinbefore.

40 55 The motor 562 will continue to cause the belts 196 and 198 to move the bill inwardly of the paper currency validator 30; and, if that bill is being moved inwardly

60 65 The motor 562 will continue to cause the belts 196 and 198 to move the bill inwardly of the paper currency validator 30; and, if that bill is being moved inwardly

at the rate of 9-3/10 of an inch per second, the leading edge of that bill will engage the actuator 164 and close the switch 162 about 450 milliseconds after that leading edge caused the actuator 158 to close the switch 156. As the switch 162 is closed, the transistor 350 will become conductive, and logic 0 will appear at the lower input of NAND gate 334, and at the cathode of diode 384, at the cathode of diode 432 in FIG. 13, at the input of inverter 446, at the cathode of diode 502, and at the middle input of NAND gate 506. The logic 0 at the lower input of NAND gate 334 will not be significant because the output of that NAND gate was, and will continue to be, logic 1. The logic 0 at the cathode of diode 384 will forward-bias that diode and cause the Vend Time Circuit 382 to remove the forward-bias on the base-emitter circuit of transistor 398 of the Vend Time Circuit 382, all as explained hereinbefore. The logic 0 at the cathode of diode 432 in FIG. 13 will forward-bias that diode; and hence capacitor 440 in the Positional Time Delay Circuit 428 will discharge to keep the voltage at the emitter of transistor 442 from reaching the Zener voltage of that transistor, all as explained hereinbefore. The logic 0 at the cathode of diode 502 will forward-bias that diode, and thus will apply logic 0 to the lower input of NAND gate 498. However, because the output of that NAND gate was logic 1, the application of logic 0 to the lower input of that NAND gate will not change that output. The logic 0 at the middle input of NAND gate 506 will not change the output of that NAND gate because conductor 324 has been applying logic 0 to the lower input of that NAND gate. The logic 0 at the input of the inverter 446 of the Further Time Delay Circuit 444 will initiate the time interval of 250 to 300 milliseconds which that Further Time Delay Circuit provides, all as explained hereinbefore.

Shortly after the leading edge of the bill causes the actuator 164 to close the switch 162, the vertical grid lines in the leading half of the portrait background of the bill will move into registry with the air gap of the magnetic head 208. That magnetic head will respond to those vertical grid lines to develop a signal which has a frequency of approximately 1150 Hertz; and the capacitor 260 will couple that signal to the base of transistor 248. That transistor and the transistor 250 will amplify that signal; and the capacitor 266 will couple the resulting amplified signal to the base of transistor 274. That transistor and the inverter 276 will square that amplified signal and then apply it to the tuned circuit of the Frequency-Sensing Circuit 280. Because that bill is an authentic U.S. one dollar bill, because the black-ink face of that bill confronts the magnetic head 208, and because the bill has the vertical grid lines in the portrait background thereof moved past the air gap of that magnetic head at a rate of about 1150 per second, a voltage will develop across the inductor 282 of that Frequency-Sensing Circuit in a manner which is substantially identical to the manner in which a voltage is developed across the inductor in the tuned circuit in Smith et al. Pat. No. 3,245,534 for Method And Apparatus For Magnetic Currency Detectors which was granted on Apr. 12, 1966. The diode 290 will apply that voltage to the base of transistor 296; and that voltage will render that transistor conductive. Thereupon, the transistor 298 will become conductive and will apply logic 0 to the upper input of NAND gate 312. The output of that NAND gate will tend to become

logic 1; but because the output of NAND gate 314 is logic 0, the output of NAND gate 312 and the voltage on conductors 324 and 325 will remain logic 0.

Approximately 188 milliseconds after the leading edge of the bill caused the actuator 164 to close the switch 162, the vertical grid lines in the leading half of the portrait background will move into register with the air gap of the magnetic head 210, and the vertical grid lines in the trailing half of that portrait background will move into register with the air gap of the magnetic head 208. Those magnetic heads will respond to those vertical grid lines to develop signals which have frequencies of approximately 1150 Hertz; and the capacitor 260 and its counterpart in the Amplifier 270 will couple those signals to the bases of transistor 248 and of its counterpart. The Amplifiers 246 and 270 will amplify the signals from the magnetic heads 208 and 210, and the Squaring Circuits 272 and 278 will square the amplified signals and apply them to the tuned circuits of the Frequency-Sensing Circuits 280 and 292. Because that bill is an authentic U.S. one dollar bill, because the black-ink face of that bill confronts the magnetic heads 208 and 210, and because that bill has the vertical grid lines in the portrait background thereof moved past the air gap of each of those magnetic heads at a rate of about 1150 per second, the diode 290 and its counterpart will supply signals to the transistors 296 and 297 which will render those transistors conductive. Thereupon, the transistors 298 and 299 will become conductive; and logic 0 signals will be applied to the upper input of NAND gate 312 and to the lower input of NAND gate 314. Logic 1 will then appear at the outputs of both of the NAND gates 312 and 314, and thus on conductors 324 and 325, at the input of inverter 316, on the upper input of NAND gate 358 in FIG. 13, at the collector of transistor 398, at the anode of diode 528, and at the lower input of NAND gate 506. The inverter 316 of the Validation Latch Circuit 310 will apply logic 0 to the lower input of NAND gate 312 and to the upper input of NAND gate 314; and that logic 0 will keep the outputs of those NAND gates at logic 1 after the vertical grid lines in the leading and trailing halves of the portrait background of the bill have been moved inwardly beyond the air gaps, respectively, of the magnetic heads 210 and 208. The Validation Latch Circuit 310 then will maintain logic 1 on conductors 324 and 325 until the transistor 398 in the Vend Time Circuit 382 is subsequently rendered conductive during the normal operation of the paper currency validator 30.

The logic 0 at the output of inverter 316 also will be applied to the cathode of diode 448 in the Further Time Delay Circuit 444 in FIG. 13; and that diode will become forward-biased to discharge the capacitor 452. This means that although the inverter 446 will keep the diode 450 back-biased, the capacitor 452 will become discharged; and hence the voltage at the emitter of transistor 458 will not be able to reach the Zener voltage of that transistor, all as explained hereinbefore. Consequently, the transistor 462 will be able to remain non-conductive, and thereby keep logic 1 on conductor 463. The logic 0 at the output of inverter 312 also will appear at the lower input of NAND gate 510.

The logic 1 on the upper input of NAND gate 358 in FIG. 12 will not be able to change the output of that NAND gate, because the switches 146, 156 and 162, the transistors 332, 342 and 350, the NAND gate 334

and the inverter 426 will coat to apply logic 0 to the lower input of that NAND gate. The logic 1 on the collector of the transistor 398 in FIG. 12 will not be able to render that transistor conductive, because the diode 384 in the Vend Time Circuit 382 is forward-biased and is causing the transistor 392 to apply zero voltage to the base of transistor 398. The logic 1 at the anode of diode 528 in FIG. 13 will not be able to forward-bias that diode, because the inverter 522 of the Reverse Relay Latch Circuit 518 is applying logic 1 to the cathode of that diode; and hence that Reverse Relay Latch Circuit will permit logic 1 to remain on the conductor 463. The logic 1 at the lower input of NAND gate 506 will not change the output of that NAND gate, because the logic 0 at the middle input of that NAND gate will cause that NAND gate to continue to provide logic 1 at the output thereof. The logic 0 at the lower input of NAND gate 510 will not change the output of that NAND gate, because the logic 0 at the upper input of that NAND gate will cause that NAND gate to continue to provide logic 1 at the output thereof. The immediately-effective results of the simultaneous passage of the vertical grid lines in the two halves of the portrait background past the air gaps of the magnetic heads 208 and 210 are the discharging of the capacitor 452 of the Further Time Delay Circuit 444 to keep the transistor 462 from being conductive, and the applying of logic 1 to the conductor 463.

Shortly after the vertical grid lines in the trailing half of the portrait background of the bill are moved inwardly beyond the air gap of the magnetic head 208, those vertical grid lines will move into engagement with the air gap of the magnetic head 210; and those vertical grid lines will coat with the latter magnetic head to develop signals. The Amplifier 270, the Squaring Circuit 278, the Frequency-Sensing circuit 292, and the Threshold Detector 308 will respond to those signals to apply logic 0 to the lower input of NAND gate 314. However, because the Validation Latch Circuit 310 can apply logic 1 to the conductor 324 only when both magnetic heads 208 and 210 are sensing vertical grid lines at the same instant, the application of the logic 0 solely to the lower input of NAND gate 314 could not be significant at any time — and doubly so when the output of that NAND gate was previously changed to logic 1, and is being held at that value by the Validation Latch circuit 310. Consequently, the sub-circuit of FIG. 11 effectively ignores the signals which develop as the trailing half of the portrait background is moved past the air gap of the magnetic head 210.

As the motor 562 and the belts 196 and 198 continue to move the bill inwardly of the paper currency validator 30, the trailing edge of that bill will move out from under the trailing edge 152 of the switch actuator 148, and will thereby permit the switch 146 to re-open. Thereupon, logic 1 will appear at the upper input of NAND gate 334, at the input of inverter 484 in FIG. 13, at the upper input of NAND gate 498, and at the upper input of NAND gate 510. The logic 1 at the upper input of NAND gate 334 will not change the output of that NAND gate because the switches 156 and 162 will still be closed and will be applying logic 0 to the middle and lower inputs of that NAND gate. The logic 1 at the upper input of NAND gate 498 will not change the output of that NAND gate because the diode 502 is maintaining logic 0 at the lower input of that NAND gate; and the logic 1 at the upper input of

NAND gate 510 will not change the output of that NAND gate because conductor 326 is applying logic 0 at the lower input of that NAND gate. The logic 1 at the input of inverter 484 will cause that inverter to apply logic 0 to the cathode of diode 490 in FIG. 13 and to the upper input of NAND gate 506. The logic 0 at the cathode of diode 490 will not change the signal applied to the input of inverter 488, because the diode 492 has been applying logic 0 to that input. The logic 0 at the upper input of NAND gate 506 will not change the output of that NAND gate because the logic 0 will continue to appear at the middle input of that NAND gate.

Continued inward movement of the bill will cause the trailing edge of that bill to move out from under the trailing edge 161 of the actuator 158, and thereby permit the switch 156 to re-open. Thereupon, logic 1 will be applied to the middle input of NAND gate 334, to the input of inverter 430, and to the cathode of diode 492. The logic 1 at the middle input of NAND gate 334 will not change the output of that NAND gate because the switch 162 will still be closed and will be applying logic 0 to the lower input of that NAND gate. The logic 1 at the cathode of diode 492 will not change the signal applied to the input of inverter 488, because the diode 490 will be applying logic 0 to the input of that inverter. The logic 1 at the input of inverter 430 will cause that inverter to apply logic 0 to the cathode of diode 434 and also to the cathode of diode 500. The logic 0 at the cathode of diode 434 will connect the upper terminal of capacitor 440 to ground via the inverter 430; but that capacitor was previously discharged via diode 432, conductor 352, transistor 350 and switch 162. The logic 0 at the cathode of diode 500 will not change the output of NAND gate 498, because the diode 502 will be applying logic 0 to the lower input of that NAND gate.

Further inward movement of the bill will cause the trailing edge of that bill to move out from under the trailing edge 168 of the actuator 166, and thereby permit the switch 162 to re-open. Thereupon, logic 1 will be applied to the lower input of NAND gate 334, to the cathode of diode 384, to the cathode of diode 432 in FIG. 13, to the input of inverter 446, to the cathode of diode 502, and to the middle input of NAND gate 506. The logic 1 at the cathode of diode 384 will back-bias that diode; and hence the capacitor 388 will begin to charge. However, the charge on that capacitor will take time to reach the Zener voltage of the transistor 392, and hence the transistor 398 will remain non-conductive for 150 milliseconds. The logic 1 at the cathode of diode 432 in FIG. 13 will back-bias that diode; but the capacitor 440 will remain discharged, because the diode 434 is forward-biased by the inverter 430. The logic 1 at the cathode of diode 502 in FIG. 13 will back-bias that diode; but the voltage at the output of NAND gate 498 will not change, because inverter 430 and diode 500 are applying logic 0 to the lower input of that NAND gate. The logic 1 at the middle input of NAND gate 506 will not change the output of that NAND gate because the inverter 484 is applying logic 0 to the upper input of that NAND gate. The logic 1 at the input of inverter 446 will cause that inverter to apply logic 0 to the cathode of diode 450, to the cathode of diode 494, and to the middle input of NAND gate 510. The logic 0 at the cathode of diode 450 will forward-bias that diode, and thereby keep the capaci-

tor 452 discharged via that diode and inverter 446. The logic 0 at the cathode of diode 494 will forward-bias that diode, and thereby coat with diode 490 to maintain logic 0 at the input of inverter 488. The logic 0 at the middle input of NAND gate 510 will not change the output of that NAND gate because the conductor 326 is applying logic 0 to the lower input of that NAND gate.

The application of logic 1 to the lower input of NAND gate 334 will cause the output of that NAND gate to become logic 0; and thereupon, logic 0 will appear at the input of inverter 426, at the upper terminal of capacitor 408 in the Gross Time Delay Circuit 400, and at the cathode of diode 532 in FIG. 13. The logic 0 at the upper terminal of capacitor 408 in the Gross Time Delay Circuit will forward-bias the diode 412, and thus will apply ground voltage to the base of transistor 402 — thereby permitting that transistor to become non-conductive. The transistor 404 then will become non-conductive to render the transistor 406 conductive; and, thereupon, the latter transistor will apply logic 0 to pin 13 of the voltage regulator 534 in FIG. 14 via conductor 422. The voltage at the pin 9 of that voltage regulator will then drop to zero, and transistor 554 will become non-conductive. At this time, the motor 562 will become de-energized; and the diode 570 will dissipate the inductive energy within that motor. However, the shaft 182, the pulleys 192 and 194, and the belts 196 and 198 will coast long enough to permit the lower runs of those belts to move the trailing edge of the bill wholly inwardly of the paper currency validator 30 and into a cash box or other bill-receiving device at the outlet of that paper currency validator.

The logic 0 at the cathode of diode 532 in FIG. 13 will forward-bias that diode; and hence logic 0 will appear at the anode of diode 526 and at the input of inverter 522. The logic 0 at the anode of diode 526 will back-bias that diode; and the logic 0 at the input of inverter 522 will cause that inverter to back-bias diodes 524 and 528. Consequently, logic 1 will continue to appear on conductor 463 and on conductor 324.

The logic 0 on the input of inverter 426 will cause that inverter to apply logic 1 to the lower input of NAND gate 358. Because logic 1 appears on conductor 325, the output of NAND gate 358 becomes logic 0; and inverter 360 applies logic 1 to the input of inverter 380 and also to the base of transistor 366 via resistor 362 and transistor 364. Thereupon, the transistor 366 will become conductive and will energize the relay coil 368 — with consequent closing of the relay contacts 372. Those relay contacts will send a vend signal to the vending machine via conductors 374 and 376.

The application of logic 1 to the input of inverter 380 will cause that inverter to apply logic 0 to the bases of transistors 332, 342 and 350 via resistors 338, 346 and 354, respectively. Thereupon, all of those transistors will become non-conductive and will remain non-conductive. This is desirable, because it will keep any further closing of any of the switches 146, 156 and 162 from changing the output state of the NAND gate 334 — whether the closing of any of those switches is due to contact bounce, to the insertion of a foreign object or to the insertion of a further bill.

The capacitor 388 in the Vend Time Circuit 382 will continue to charge; and, about 150 milliseconds after the switch 162 re-opened, the voltage at the emitter of transistor 392 will exceed the Zener voltage of that

transistor, and the transistor 398 will become conductive. The resulting logic 0 on conductors 325 and 324 will be applied to the upper input of NAND gate 358, to the input of inverter 316 in FIG. 11, to the anode of diode 528 in FIG. 13, and to the lower input of NAND gate 506. The logic 0 at the anode of diode 528 will back-bias that diode; and the logic 0 at the lower input of NAND gate 506 will leave the output of that NAND gate unchanged. The logic 0 at the upper input of NAND gate 358 will make the output of that NAND gate logic 1; and inverter 360 will respond to that logic 1 to apply logic 0 to the input of inverter 380 and to the base of transistor 366. Inverter 380 will apply logic 1 to the bases of transistors 332, 342 and 350 via resistors 338, 346 and 354, respectively; but those transistors will remain non-conductive because all of the switches 146, 156 and 162 will be open. The logic 0 at the base of transistor 366 will render that transistor non-conductive; and, thereupon, the relay coil 368 will become deenergized, and the diode 370 will dissipate the inductive energy in that relay coil. At this time, the relay conducts 372 will re-open, and thus will terminate the vend signal which they had been applying to the vending machine.

The logic 0 at the input of inverter 316 will cause that inverter to apply logic 1 to the lower input of NAND gate 312, to the upper input of NAND gate 314, to the cathode of diode 448 in FIG. 13, and to the lower input of NAND gate 510. The logic 1 at the cathode of diode 448 in FIG. 13 will back-bias that diode; but, because inverter 446 is maintaining logic 0 at the cathode of diode 450, the capacitor 452 will continue to remain in its discharged state. The logic 1 at the lower input of NAND gate 510 will not change the output of that NAND gate, because the inverter 446 will continue to apply logic 0 to the middle input of that NAND gate. The logic 1 at the lower input of NAND gate 312 and the logic 1 at the upper input of NAND gate 314 will cause those NAND gates to develop logic 0 at the outputs thereof. The inverter 316 will respond to that logic 0 to maintain logic 1 at the lower input of NAND gate 312 and at the upper input of NAND gate 314; and hence the Validation Latch Circuit 310 will act to maintain logic 0 on the conductors 325 and 324. The transistor 398 will respond to that logic 0 to become non-conductive, even though the voltage at the base of that transistor tends to forward-bias that transistor. The logic 0 at the anode of diode 528 will enable that diode to remain back-biased; and the logic 0 at the lower input of NAND gate 506 will enable the output of that NAND gate to remain logic 1. At this time, the paper currency validator 30 will be in its standby condition; and it will remain in that condition until one of the switches 146, 156 or 152 is again closed.

If a person were to insert the leading edge of a bill into the paper currency validator 30, and were then to attempt to keep that bill from moving inwardly at the normal rate of speed of between 9-1/10th and 9-5/10ths of an inch per second, the amplitude of the output voltage of the A.C. generator 560 would decrease slightly. The transistor 538 would amplify that decrease in voltage and would provide an appreciable change in the voltage at the movable contact of the potentiometer 544. The voltage regulator 534 would then materially increase the value of the positive voltage which it applies to the base of transistor 554 to enable that trans-

sistor to materially increase the current flowing through the motor 562.

That increase in current will increase the voltage at the emitter of that transistor, and hence at the upper input of the differential amplifier 574. The movable contact of the potentiometer 580 will usually be set to establish a reference voltage, at the lower input of that differential amplifier, which will be higher than the normal voltage at the emitter of transistor 554, and which will correspond to the voltage that will develop at that emitter if a person retards or halts the inward movement of a bill. As long as the current flowing through the motor 562 is normal, the voltage at the emitter of transistor 554 will be below the reference voltage at the lower input of the differential amplifier 574, and hence the output of that differential amplifier will be logic 0. However, if the current flowing through the motor 562 increases to the point where the voltage at the emitter of transistor 554 is greater than the reference voltage at the lower input of the differential amplifier 574, the output of that differential amplifier will change to logic 1; and the inverter 586 will apply logic 0 to conductor 328. That logic 0 will forward-bias the diodes 320 and 322 in FIG. 11; and hence the bases of transistors 298 and 299 will be grounded. Consequently, those transistors could not become conductive even if the magnetic heads 208 and 210 were to coact with the Amplifiers 246 and 270, the Squaring Circuits 272 and 278, and the Frequency-Sensing Circuits 280 and 292 to render the transistors 296 and 297 of the Threshold Detectors 294 and 308 conductive. This means that if a person appreciably retards the rate of movement of a bill inwardly of the paper currency detector 30, the Current-Sensing Circuit 572 in FIG. 14 will keep that paper currency validator from developing a validation signal on conductors 324 and 325; and hence the motor 562 will reverse, and will cause the bill to be backed out of that paper currency validator in the same way in which that motor reverses and backs out a bill that is inserted with its green-ink face up, all as explained hereinafter.

Because the Amplitude-Responsive Control Circuit 533 of FIG. 14 amplifies the output voltage of the A.C. generator 560, even a visually-imperceptible retardation in the speed of an inserted bill can cause the voltage regulator 534 to materially increase the voltage at the emitter of transistor 554. This means that the Current-Sensing Circuit 572 can inhibit the application of a validation signal to the conductor 324 even if the vertical grid lines in the portrait background of a bill are permitted to move past the air gaps of the magnetic heads 208 and 210 at a rate just slightly less than the pre-set rate. As a result, that Current-Sensing Circuit can defeat efforts, to attain unauthorized operation of the paper currency validator 30, which the Frequency-Sensing Circuits could not defeat.

The Current-Sensing Circuit 572 is particularly important where the paper currency validator 30 is modified to enable it to distinguish between U.S. one dollar bills and U.S. five dollar bills. Because the spacing between the vertical grid lines in the portrait background of a U.S. five dollar bill is appreciably greater than the spacing between the vertical grid lines in the portrait background of a U.S. one dollar bill, it is possible to equip the paper currency validator 30 with Frequency-Sensing Circuits which sense one center frequency that corresponds to one dollar bills and to equip that paper currency validator with other Frequency-Sensing cir-

cuits which sense a second and different center frequency that corresponds to five dollar bills. If a person were able to retard the rate at which the motor 562 moved a one dollar bill inwardly of the paper currency validator 30 to a value which caused the vertical grid lines in the portrait background of that bill to move past the air gaps of the magnetic heads 208 and 210 at the same rate at which the vertical grid lines in the portrait background of a five dollar bill are normally moved past those air gaps, the vertical grid lines in the portrait background of the one dollar bill could generate signals that closely simulated the signals which the vertical grid lines in the portrait background of a five dollar bill could generate. As a result, the frequency-sensing circuits of that modified paper currency validator might be unable to defeat such an attempt to effect unauthorized operation of that paper currency validator.

However, the Current-Sensing Circuit 572 would sense the increased motor current which transistor 538 and voltage regulator 534 would cause the transistor 554 to supply to the motor 562; and that Current-Sensing Circuit and inverter 586 would develop logic 0 on conductor 328 and at the cathodes of diodes 320 and 322 — thereby defeating such an attempt to effect unauthorized operation of the paper currency validator 30. All of this means that even if the amplifiers, the squaring circuits, the frequency-sensing circuits, and the initial transistors of the threshold detectors in the five dollar section of a paper currency validator were to respond to the signals which were developed by retarding the inward movement of a one dollar bill, the Current-Sensing Circuit 572 would forward-bias the diodes 320 and 322, and thereby keep the bases of transistors 298 and 299 at logic 0. In such event, the NAND gates 312 and 314 would continue to maintain logic 0 on conductors 324 and 325, and would thereby prevent the development of a validation signal.

As indicated particularly by FIG. 11, the inductors and the capacitors of the tuned circuits of the Frequency-Sensing Circuits 280 and 292 are fixed, rather than adjustable, inductors and capacitors. This is important, because the stability of fixed inductors tends to be greater than the stability of adjustable inductors of corresponding quality, and the stability of fixed capacitors tends to be greater than the stability of adjustable capacitors of corresponding quality. Further, the cost of variable inductors is greater than the cost of fixed inductors of corresponding quality, and the cost of adjustable capacitors is higher than the cost of corresponding quality fixed capacitors.

Even where fixed inductors and fixed capacitors are used in the tuned circuits of the Frequency-Sensing Circuits 280 and 292, the manufacturing tolerances of such inductors can be as high as plus or minus 2 percent, and the manufacturing tolerances of such capacitors can be as high as plus or minus 5 percent. Because each of the tuned circuits, in the Frequency-Sensing Circuits 280 and 292, has two capacitors and an inductor, the total tolerance variation in either of those tuned circuits could run as high as plus or minus 10 percent and would commonly run as high as 7 percent. This means that even if the circuit boards of all of the paper currency validators 30, which were made in accordance with the principles and teachings of the present invention, were fabricated with components which had the same nominal values, the center frequencies of

the tuned circuits of the Frequency-Sensing Circuits 280 and 292 of those circuit boards could vary as much as plus or minus 10 percent and would commonly run as high as plus or minus 7 percent.

The present invention makes it possible to gain the important benefits of greater stability and of lower costs, which the use of fixed inductors and of fixed capacitors affords, by making it possible to set, and thereafter maintain, the speed of the motor 562 at a value which is a function of the center frequencies of the tuned circuits of the Frequency-Sensing Circuits 280 and 292. Specifically, the present invention contemplates the use of a variable frequency oscillator to determine the center frequency of each circuit board for a currency validator 30, and then contemplates the adjusting of the speed of the motor 562 to enable the vertical grid lines in the portrait background of a bill to pass the air gaps of the magnetic heads 208 and 210 at that frequency. Because the output shaft 203 of the motor 562 is directly geared to the pulleys 192 and 194, the speed of the belts 196 and 198 is directly proportional to the speed of that motor; and hence it is possible to set any desired belt speed by approximately setting the motor speed. The voltage across the series-connected resistors 556 and 558 will be a close indication of the speed of the motor 562; and, consequently, it is only necessary to connect the voltage across those series-connected resistors to an appropriate read out, and then adjust the position of the movable contact of the potentiometer 544 to set the desired motor speed. In this way, the present invention makes it possible to make the speed of the inserted bills a function of the center frequencies of the tuned circuits of the Frequency-Sensing Circuits 280 and 292 rather than to make those center frequencies as a function of the speed of those bills. Not only does the present invention provide greater stability and less cost for its Frequency-Sensing Circuits, but it avoids the cost and bulk of a synchronous motor.

Once the speed of the motor 562 has been set, by appropriate adjustment of the position of the movable contact of the potentiometer 544, the sub-circuit of FIG. 14 will hold that speed fixed within very close limits — despite line voltage variations and despite temperature variations varying from 40 to 160° Fahrenheit. For example, if the speed of the motor 562 tends to decrease, the amplitude of the A.C. voltage developed by the A.C. generator 560 also will decrease, and hence the rectified and filtered voltage which is applied to the base of transistor 538 will be lower than normal. The resulting decrease in conductivity of that transistor will appreciably reduce the voltage at the pin 4 of the voltage regulator 534; and hence that voltage regulator will cause the voltage at the pin 9 to increase materially. Transistor 554 will respond to the material increase in voltage at the base thereof to materially increase the current flowing through the motor 562; and that motor will respond to that materially increased current to promptly increase the speed thereof to its pre-set value. As the speed of the motor 562 approaches its pre-set value, the voltage at pin 9 will return to its normal level; and hence the amount of current which the transistor 554 will permit to flow through that motor will return to a level which will enable that motor to operate at its pre-set speed.

On the other hand, if the speed of the motor 562 tends to increase rather than decrease, the amplitude

of the A.C. voltage which is developed by the A.C. generator 560 will increase; and hence the base of transistor 538 will receive an increased value of rectified and filtered voltage. The increased conductivity of that transistor will cause voltage at the movable contact of potentiometer 544 to increase appreciably; and the voltage regulator 534 will respond to that appreciably increased voltage to materially reduce the value of the voltage at the pin 9 thereof. The resulting material decrease in conductivity of the transistor 554 will materially decrease the value of the current flowing through the motor 562; and that motor will respond to that materially reduced current to promptly decrease the speed thereof to its pre-set value. As the speed of the motor 562 approaches its pre-set speed, the voltage at pin 9 will tend to return to its normal value, and hence the amount of current which the transistor 554 will permit to flow through that motor will return to a level which will enable that motor to operate at its pre-set speed. In this way, the sub-circuit of FIG. 14 will hold the speed of the motor 562 essentially constant at any pre-set value which is selected by an appropriate setting of the movable contact of the potentiometer 544.

Pin 2 of the voltage regulator 534 will coact with the resistor 558 to reduce the value of the signal at the pin 9 of that voltage regulator if the voltage at the pin 2 ever exceeds a predetermined value. This is desirable, because it will keep the value of the current flowing through motor 562 and the transistor 554 from exceeding a safe level. For example, if something were to happen to the motor 562 which tended to cause that motor to draw an excessive amount of current, the voltage at the upper terminal of the resistor 558 would rise; and, if that voltage reached seven-tenths of a volt, the voltage regulator 534 would reduce the voltage at the pin 9, and thus the current flowing through that motor, until the voltage at the upper terminal of that resistor fell below seven-tenths of a volt. In this way, the sub-circuit of FIG. 14 can respond to unduly-large values of motor current to reduce the conductivity of transistor 554, and thereby reduce the value of the current flowing through the motor 562.

The Frequency-Responsive Control Circuit 588 of FIG. 15 is an acceptable substitute for the Amplitude-Responsive Control Circuit 533 of FIG. 14. That frequency-responsive control circuit is not, per se, a part of the present invention; and it is disclosed herein solely to illustrate the adaptability of the circuitry of FIGS. 11-13 to various speed-regulating control systems.

The output of the A.C. generator 560 in FIG. 15 is applied to the base of transistor 590 by resistor 592; and the diode 598 bypasses to ground the negative-going components of that output. The transistor 590 will respond to the signals from the A.C. generator 560 to develop a square wave at the collector thereof which has a frequency that is equal to the frequency of those signals; and that square wave will be differentiated by the differentiator which consists of capacitor 600 and resistor 602. The resulting differentiated signal will be supplied to pin 2 of the one-shot 606; and that one-shot will trigger on the negative-going edges of that differentiated signal. The output of the one-shot 606 appears at the pin 3 thereof, and that output is applied to the base of transistor 630 by resistor 632. That output is a square wave with positive-going pulses that have durations less than one-half the duration of each cycle of

the output of the A.C. generator 560. In one embodiment of the Frequency-Responsive Control Circuit 588 of FIG. 15, the duration of each positive-going pulse is six-tenths of a millisecond whereas the duration of each cycle of the output of the A.C. generator 560 is one and one-quarter of a millisecond. The transistor 630 will invert the square wave; and each negative-going pulse of that inverted square wave will have a duration of about six-tenths of a millisecond.

Resistors 626, 634, 636, 638 and capacitors 640 and 642 constitute an integrating network; and that integrating network will integrate the negative-going pulses of the square wave at the collector of transistor 630. The output of that integrating network is applied to the upper input terminal of the operational amplifier 650; and that output is a D.C. voltage with negligible ripple. The value of that D.C. voltage is proportional to the ratio of the duration of the negative-going pulses of the square wave to the duration of each cycle of the A.C. signal from the A.C. generator 560. Consequently, that D.C. voltage is proportional to the frequency of the signal which is developed by that A.C. generator.

The upper input terminal of the operational amplifier 650 is the non-inverting input of that operational amplifier, whereas the lower input terminal of that operational amplifier is an inverting input. Resistors 644 and 648 and the potentiometer 646 establish a reference voltage which is applied to the lower input of the operational amplifier 650; and hence the output of that operational amplifier is proportional to the difference between the voltages which are applied to the upper and lower inputs thereof. Because the D.C. voltage which is applied to the upper input of the operational amplifier 650 is proportional to the frequency of the signal developed by the A.C. generator 560, whereas the voltage which is applied to the lower input of that operational amplifier is a reference voltage, the output of that operational amplifier is an error voltage which is proportional to the extent to which the speed of the motor 562 varies from its selected value.

If the speed of the motor 562 tends to decrease, the frequency of the signal which is developed by the A.C. generator 560 will also decrease, and hence the voltage that is supplied to the upper terminal of the operational amplifier 650 will tend to decrease. The output of that operational amplifier will, however, increase, and will thereby apply a signal to the base of transistor 670 which will tend to render that transistor more conductive — with a corresponding increase in the value of the current flowing through the motor 562. As the speed of that motor increases to its pre-set value, the error signal will decrease and the conductivity of the transistor 670 — and hence the value of the current flowing through the motor 562 — will return to their pre-set levels. On the other hand, if the speed of the motor 562 tends to increase, the frequency of the signal which is developed by the A.C. generator 560 also will increase, and hence the voltage that is applied to the upper input of operational amplifier 650 will tend to increase. The output of that operational amplifier will, however, decrease, and will thereby apply a signal to the base of transistor 670 which will tend to render that transistor less conductive — with a corresponding decrease in the value of the current flowing through the motor 562. As the speed of that motor decreases to its pre-set value, the error signal will decrease and the conductivity of the transistor 670 — and hence the value of the current

flowing through the motor 562 — will return to their pre-set levels. The subcircuit of FIG. 15, like the subcircuit of FIG. 14 is an underdamped system, and thus will provide a desirably rapid response.

5 The transistor 624 is connected in parallel with the transistor 630, and it can be rendered conductive to shunt the transistor 630 and thereby halt the supplying of current to the motor 562. The transistor 624 will be rendered conductive, and this will halt the supplying of 10 current to the motor 562, whenever the output of NAND 334 in FIG. 12 is logic 0. At such time, the Gross Time Delay Circuit 400 will be applying logic 0 to the conductor 422; and the inverter 620 in FIG. 15 will respond to that logic 0 to apply logic 1 to the base 15 of transistor 624 — thereby rendering that transistor conductive. Consequently, as long as the output of NAND gate 334 in FIG. 12 is logic 0, the motor 562 will be at rest. However, when the output of NAND gate 334 is logic 1, as it will become when any one of the switches 146, 156 and 162 is closed, the inverter 620 in FIG. 15 will apply logic 0 to the base of transistor 624 — thereby rendering that transistor non-conductive. Thereupon, the Frequency-Responsive Control Circuit 588 will energize the motor 562, and 20 will cause it to operate at the speed pre-set by the setting of the movable contact of potentiometer 646.

The voltage at the emitter of transistor 670, of the Frequency-Responsive Control Circuit 588 in FIG. 15, is applied to the upper input of the differential amplifier 574 of the Current-Sensing Circuit 572 — in the same way in which the voltage at the emitter of transistor 554 of the Amplitude-Responsive Control Circuit 533 in FIG. 14 is applied to the upper input of that differential amplifier. The resistors 578 and 582 and the potentiometer 580 in FIG. 15 apply a reference voltage to the lower input of the differential amplifier 574 — in the same way in which the identically-numbered resistors and potentiometer supply a reference voltage to the lower input of the differential amplifier 574 in FIG. 35 14. Consequently, the differential amplifier 574 in FIG. 15 can cause the inverter 586 to forward-bias the diodes 320 and 322 in FIG. 11 if the current flowing through the motor 562 exceeds a predetermined value. As a result, the Current-Sensing Circuit 572 in FIG. 15, 45 like the identically-numbered Current-Sensing Circuit in FIG. 14, can inhibit validation if a person inserts a bill into the paper currency validator 30, and then attempts to retard or halt the inward movement of that bill.

50 If a person were, deliberately or inadvertently, to insert bill so that black-ink face thereof was directed downwardly rather than upwardly, the paper currency validator 30 would move that bill inwardly thereof, but the magnetic heads 208 and 210 would be unable to develop signals which could cause the Frequency-Sensing Circuits 280 and 292 to actuate the Threshold Detectors 294 and 308. As a result, the NAND gates 312 and 314 would continue to maintain a logic 0 at the outputs thereof, and would thereby cause the inverter 316 in FIG. 11 to maintain logic 1 on conductor 326 — and thus at the cathode of diode 448 in the Further Time Delay Circuit 444 in FIG. 13 and also at the lower input of NAND gate 510 in the Switch-Checking Circuit 508. 55 As the leading edge of the inverted bill engages the actuator 164 to close the switch 162, logic 0 will appear on the conductor 352, and hence at the input of inverter 446 of the Further Time Delay Circuit 444 in 60 65

FIG. 13. At such time, both of the diodes 448 and 450 will be back-biased; and hence Further Time Delay Circuit 444 will initiate its time delay of from 250 to 300 milliseconds.

Because the magnetic heads 208 and 210 will be unable to coact with the green-ink face of a dollar bill to develop signals which could cause the Frequency-Sensing Circuits 280 and 292 to actuate the Threshold Detectors 294 and 308, the logic 1 on conductor 326 will not change to logic 0 during the time delay of the Further Time Delay Circuit 444. Consequently, at the end of that time delay, the voltage across the capacitor 452 of that Further Time Delay Circuit will exceed the Zener voltage of transistor 458. Thereupon, the transistor 462 will become conductive and will change the logic 1 on the conductor 463 to logic 0. The inverter 520 in the Reverse Relay Latch Circuit 518 will respond to the consequent application of logic 0 to the input thereof to apply logic 1 to the base of transistor 476, thereby rendering that transistor conductive. Current then will flow through the relay coil 468, transistor 476 and resistor 478 to ground, and will thereby energize that relay coil. The movable relay contacts 470 and 472 in FIG. 14 will promptly shift into engagement with the right-hand fixed relay contacts 470 and 472, respectively, and thereby cause the motor 562 to reverse its direction of rotation. The belts 196 and 198 will stop moving the bill inwardly of the paper currency validator 30 and, instead, will start moving that bill outwardly of that paper currency validator.

The NAND gate 334 in FIG. 12 will have logic 1 at the output thereof; and the resulting logic 1 at the cathode of diode 532 in FIG. 13 will back-bias that diode. When the NAND gate 334 changed the output thereof to logic 1 and before the Further Time Delay Circuit 444 rendered the transistor 462 conductive, the diode 532 became back-biased and could no longer back-bias the diode 526. At that time, the inverter 520 forward-biased the latter diode, and this enabled that diode to apply logic 0 to the input of inverter 522 — to back-bias both of the diodes 524 and 528. However, when the Further Time Delay Circuit 444 rendered the transistor 462 conductive, and the output of inverter 520 became logic 1, the diode 526 became back-biased and could no longer apply logic 0 to the input of inverter 522. Thereupon the voltage at that input became logic 1, and the resulting logic 0 at the output of that inverter forward-biased both of the diodes 524 and 528. The forward-biasing of diode 524 will hold conductor 463 at logic 0, and the forward-biasing of diode 528 will hold conductor 324 at logic 0. This means that the Reverse Relay Latch Circuit 518 will hold logic 0 on both conductors 463 and 324 — thereby keeping the relay contacts 470 and 472 in the "reverse" position, and inhibiting or cancelling any validation signal — until all of the switches 146, 156 and 162 re-open to permit logic 0 to re-appear at the output of NAND gate 334. In doing so, the Reverse Relay Latch Circuit 518 effectively latches the reverse relay coil 468 in energized position, and inhibits or cancels any validation signal.

As the leading edge of the bill is moved outwardly from under the actuator 164 of the switch 162, that switch will re-open; and logic 1 will be applied to the lower input of NAND gate 334, to the cathode of diode 384, to the cathode of diode 432, to the input of inverter 446, to the cathode of diode 502, and to the middle input of NAND gate 504. The NAND gate 334 will

not respond to that logic 1 because logic 0 still appears at the middle and upper inputs thereof. The logic 1 at the cathode of diode 384 in FIG. 12 will back-bias that diode, and that back-biasing will initiate the time delay of the Vent Time Circuit 382; but the transistor 398 will not become conductive, because logic 0 appears on conductor 325, and thus at the collector of that transistor. The logic 1 at the cathode of diode 432 can not have any effect at this time because the conductor 463 has logic 0 on it. The application of logic 1 to the input of inverter 446 will forward-bias the diode 450, and thus will enable the capacitor 452 to discharge via that diode and that inverter. The application of logic 1 to the cathode of diode 502 will back-bias that diode but that back-biasing can not have any effect at this time because the conductor 463 has logic 0 on it; and the logic 1 at the middle input of NAND gate 506 will not be significant at this time because the conductor 463 has logic 0 on it.

As the belts 196 and 198 continue to move the bill outwardly of the paper currency validator 30, the leading edge of that bill will move outwardly from under the actuator 158 of the switch 156, thereby permitting a logic 1 to appear at the middle input of NAND gate 334, at the input of inverter 430, and at the cathode of diode 492. The NAND gate 334 will not be able to respond to that logic 1, because logic 0 still appears at the upper input thereof. The logic 1 at the input of inverter 430 will cause that inverter to forward-bias the diodes 434 and 500, and the logic 1 at the cathode of diode 492 will back-bias that diode. The forward-biasing of diode 434 will keep the capacitor 440 discharged; but the forward-biasing of diode 500 and the back-biasing of diode 492 will not be significant at this time because the conductor 463 has logic 0 on it.

When the leading edge of the bill is moved outwardly from under the actuator 148 of switch 146, logic 1 will appear at the upper input of NAND gate 334, at the input of inverter 484, at the upper input of NAND gate 498, and at the upper input of NAND gate 510. The logic 1 at the upper inputs of NAND gates 498 and 510 will not be significant at this time because the conductor 463 has a logic 0 on it; and, similarly, the logic 1 at the input of inverter 484 will not be significant at this time because that conductor has logic 0 on it. However, the NAND gate 334 will respond to the logic 1 at all of the inputs thereof to apply logic 0 to the input of inverter 426, to the upper terminal of capacitor 408 in the Gross Time Delay Circuit 400, and to the cathode of diode 532 in FIG. 13. Inverter 426 will apply logic 1 to the lower input of NAND gate 358; but that NAND gate will continue to apply logic 1 to the input of inverter 360, because the logic 0 on conductor 325 will be applied to the upper input of that NAND gate. The logic 0 at the upper terminal of capacitor 408 in FIG. 12 will cause the transistors 402 and 404 to become non-conductive, and, thereupon, the transistor 406 will again become conductive, all as explained hereinbefore. The resulting logic 0 at the pin 13 of the voltage regulator 534 in FIG. 14 will de-energize the motor 562; and the diode 570 will dissipate the inductive energy in that motor. However, the shaft 182, the pulleys 192 and 194, and the belts 196 and 198 will coast long enough to cause the lower runs of those belts to move the bill wholly outwardly of those belts. The logic 0 at the cathode of diode 532 will forward-bias that diode; and the inverter 522 will respond to the re-

sulting logic 0 at the input thereof to back-bias diodes 524 and 528. At this time, the outer edge of the bill will be projecting outwardly beyond the outer end of the platform 32; and that bill can then be inverted and again introduced into the paper currency validator 30.

As the capacitor 452 is discharged, when the switch 162 re-opened, the voltage at the emitter of transistor 458 fell below the Zener voltage of that transistor; and hence transistor 462 became non-conductive. However, the inverter 522 of the Reverse Relay Latch Circuit 518 was forward-biasing the diode 524; and hence that diode kept logic 0 on the conductor 463. This was desirable, because it enabled the inverter 520 and the transistor 476 to keep the reverse relay coil 468 energized until the bill was moved wholly outwardly of the paper currency validator 30.

At the time the NAND gate 334 applied logic 0 to the cathode of diode 532 in FIG. 13 to forward-bias that diode, the diode 524 was the only component which was grounding the conductor 463. Consequently, when the forward-biased diode 532 caused the inverter 522 to back-bias the diode 524, logic 1 appeared on the conductor 463. The inverter 520 responded to that logic 1 to apply logic 0 to the cathode of diode 526 and to the base of transistor 476 — thereby back-biasing that diode and rendering that transistor non-conductive. Thereupon, the relay coil 468 became de-energized, and the diode 474 dissipated the inductive energy within that relay coil. The consequent return of the relay contacts 470 and 472 to the forward position of FIG. 14 places the paper currency validator in its stand by condition.

The inward movement of the bill was halted, and the outward movement of that bill was begun, while that bill was underlying all of the switch actuators 148, 158 and 164. Consequently, there was no need for the outer edge of that bill to coact with the trailing edge of any of those switch actuators to raise that switch actuator. However, the trailing edges of those switch actuators have configurations and inclinations which enable the outer edge of an outwardly-moving bill to readily raise those switch actuators.

The overall result of the insertion of a bill into the paper currency validator 30, while that bill is in inverted position, is the movement of that bill inwardly of that paper currency validator until approximately 250 to 300 milliseconds after the leading edge of that bill closes the switch 162. Thereupon the motor 562 will start operating in the reverse direction, and the bill will be backed out of that paper currency validator. Because the sub-circuit of FIG. 11 will not develop a validation signal, the NAND gate 358 in FIG. 12 will not be able to apply logic 0 to the input of inverter 360; and hence that inverter will not be able to cause the transistor 366 to become conductive to energize the vend relay 368. Consequently, the vend relay contacts 372 will remain open, and a vend signal will not be sent to the vending machine.

If a person were to inadvertently insert a U.S. two dollar bill, a U.S. five dollar bill, or an even high denomination U.S. bill, the sub-circuit of FIG. 11 would not cause the NAND gates 312 and 314 to develop a logic 1 on the conductors 324 and 325. As a result, the paper currency validator 30 would permit the leading edge of such a bill to close the switch 162 and to continue to move inwardly for approximately 250 to 300

milliseconds; but thereafter would reverse the motor 562 and cause it to back that bill out of that paper currency validator. Neither a validation signal nor a vend signal would be developed; and hence the vending machine would not be actuated.

If a person were to insert just the upper half of a bill, and if that upper half were disposed in alignment with switch actuator 148 and magnetic head 210, that half bill would engage that switch actuator and thereby effect closing of the switch 146. The closing of that switch would cause the NAND gate 334 to develop a logic 1 at the output thereof; and the Gross Time Delay Circuit 400 would respond to that logic 1 to start the motor 562 operating in the forward direction. As that half bill was moved inwardly of the paper currency validator 30, it would not energize the switch actuator 158 or the switch actuator 164, and it would not engage the magnetic head 208. However, that half bill would engage the magnetic head 210; and the vertical grid lines in both the leading and trailing halves of the portrait background would engage the air gap of that magnetic head.

As the vertical grid lines in the leading half of the portrait background of the half bill were moved into engagement with the air gap of the magnetic head 210, that magnetic head developed signals which the Amplifier 270, the Squaring Circuit 278, the Frequency-Sensing Circuit 292, and the Threshold Detector 308 responded to and applied logic 0 to the lower input of NAND gate 314. However, because the Threshold Detector 294 was still applying logic 1 to the upper input of NAND gate 312, logic 0 continued to appear on the conductors 324 and 325 and at the input of inverter 316. Similarly, when the vertical grid lines in the trailing half of the portrait background of the half bill subsequently engaged the air gap of the magnetic head 210, that magnetic head developed signals which the Amplifier 270, the Squaring Circuit 278, the Frequency Sensing Circuit 292, and the Threshold Detector 308 responded to and applied logic 0 to the lower input of NAND gate 314. However, because the Threshold Detector 294 was still applying logic 1 to the upper input of NAND gate 312, logic 0 continued to appear on the conductors 324 and 325 and at the input of inverter 316. Consequently, neither a validation signal nor a vend signal was developed.

Because the half bill did not engage the actuator 158 for the switch 156 or the actuator 164 for the switch 162, the output of NAND gate automatically changed back to logic 0 when the trailing edge of the bill was moved inwardly beyond the trailing edge 152 of the switch actuator 148. Consequently, the motor 562 came to rest; and the half bill was not returned to the person who inserted it. Instead, that half bill remained in position within the paper currency validator 30; and it will respond to the insertion of a further bill to move wholly inwardly of the paper currency validator 30 and into the cash box or other bill-receiving device.

If a person were to insert just the lower half of a bill, and if that lower half were disposed in alignment with the switch actuators 158 and 164 and with the magnetic head 208, that half bill would engage the switch actuator 158 and thereby effect closing of the switch 156. The closing of that switch would cause the NAND gate 334 to develop a logic 1 at the output thereof; and the Gross Time Delay Circuit 400 would respond to that logic 1 to start the motor 562 operating in the for-

ward direction. As that half bill was moved inwardly of the paper currency validator 30, it would engage the switch actuator 164 but would be unable to engage the switch actuator 148. At the instant that half bill closes the switch 156, the conductor 336 would apply logic 1 to the upper input of NAND gate 498; and the conductor 352 would be applying logic 1 to the cathode of diode 502 while the inverter 430 would be applying logic 1 to the cathode of diode 500. Consequently, those diodes would be back-biased, and would thereby permit logic 1 to appear at the lower input of NAND gate 498; and that logic 1 would coact with the logic 1 at the upper input of that NAND gate to make the output of that NAND gate logic 0. Thereupon, logic 0 would appear on conductor 463 — with consequent reversal of the motor 562.

The positioning of the magnetic heads 208 and 210 so they will be in register with diagonally-displaced quadrants of the portrait background of each inserted bill is desirable, because it will permit the acceptance of an authentic U.S. one dollar bill which has the black-ink face thereof exposed to those magnetic heads — whether the top of that portrait background engages the magnetic head 208 or the magnetic head 210. In either case both magnetic heads will sense vertical grid lines at the same time, and thus will be able to effect the development of a validation signal. In this way, the paper currency validator 30 avoids all need of precise orientation of the bill on the platform 32.

If a person were, deliberately or inadvertently, to insert a second bill immediately after the trailing edge of a first bill had been drawn into the paper currency validator 30, the switch 146 would be closed by the leading edge of the second bill while the trailing edge of the first bill was still holding the switch 162 closed. At this time, the switches 146 and 162 would be closed but the switch 156 would be open. The resulting logic 0 on conductor 336 would enable the inverter 484 to apply logic 1 to the cathode of diode 490 and thereby back-bias that diode; and the resulting logic 0 on conductor 352 would enable the inverter 446 to apply logic 1 to the cathode of diode 494 and thereby back-bias that diode. The logic 1 on conductor 344 would be back-biasing the diode 492; and hence all of diodes 490, 492, and 494 would be back-biased and would permit logic 1 to appear at the input of inverter 488. The resulting logic 0 at the cathode of diode 530 would apply logic 0 to conductor 463; and, thereupon, the Reverse Relay Latch Circuit 518 would effect energization of the relay coil 468. The relay contacts 470 and 472 would then shift to their reverse positions, and the motor 562 would reverse direction and cause both of the bills to be backed outwardly of the paper currency validator 30. In addition, the Reverse Relay Latch Circuit 518 would apply logic 0 to the cathode of diode 528 to forward-bias that diode; and the resulting logic 0 on conductor 324 would cancel the validation signal which was developed by the first-inserted bill. Consequently, both bills will be moved outwardly of the paper currency validator 30, and the validation signal which was established by the first-inserted bill will be cancelled. In this way, that person will be kept from obtaining the change, product, or service from the vending machine to which the paper currency validator is connected.

In the event a person inserts a bill, which has a tape or other "tail" attached thereto that is in register with

the actuator 148 of the switch 146 but is not in register with the actuator 158 of the switch 156, the trailing edge of that bill will successively move out of engagement with the actuators 148 and 158, but the tape or other tail will remain in engagement with the actuator 148. As soon as the switch 156 re-opens, the conductor 344 will apply logic 1 to the cathode of diode 492 and thereby back-bias that diode; and, because both of the switches 146 and 162 are held closed, the inverter 484 will be back-biasing the diode 490 and the inverter 446 will be back-biasing the diode 494. Consequently, logic 1 will develop at the input of inverter 488; and the resulting logic 0 at the cathode of diode 530 will forward-bias that diode, and thereby apply logic 0 to the conductor 463. Thereupon, the motor 562 will reverse its direction of rotation, and the diode 528 will cancel any validation signal on conductors 324 and 325. In this way, the paper currency validator 30 will keep a person from obtaining the change, product or service from the vending machine with which that paper currency validator is associated, and also will effect the return of the tail-equipped bill to that person.

If a person were to insert just a short length of a bill, or were to insert a short length of a piece of paper, that short length would initially close the switch 146 to start the motor 562; and then would close the switch 156. As the motor 562 continued to move that short length inwardly, the trailing edge of that short length would move out of engagement with the actuator 148 of the switch 146, and would thereby permit reopening of that switch. At such time, the conductor 336 would apply logic 1 to the upper input of NAND gate 498; and the conductor 352 would be applying logic 1 to the cathode of diode 502 while the inverter 430 would be applying logic 1 to the cathode of diode 500. Consequently, those diodes would be back-biased, and would thereby permit logic 1 to appear at the lower input of NAND gate 498; and that logic 1 would coact with the logic 1 at the upper input of that NAND gate to make the output of that NAND gate logic 0. Thereupon logic 0 would appear on conductor 462 — with consequent reversal of the motor 562. This means that even if a person inserted the central portion of authentic bill, the paper currency validator 30 would reverse the motor 562 and send that partial length of bill back to that person. As a result, that person would be unable to obtain change, product or services from the vending machine with which the paper currency validator 30 is associated.

If a person were to insert a bill which had a hole or opening therein in alignment with the actuator 164 of the switch 162, that bill would be moved inwardly of the paper currency validator 30 and would cause the sub-circuit of FIG. 11 to develop a validation signal on the conductors 324 and 325. If that hole permitted the actuator 164 of the switch 162 to move downwardly to switch-opening position after the trailing edge of that bill had moved past the actuator 148 of switch 146 but while that trailing edge was holding the actuator 158 of switch 156 in closed-switch position, the diodes 500 and 502 would be back-biased to permit logic 1 to appear at the lower input of NAND gate 498 while logic 1 was being applied to the upper input of that NAND gate by the conductor 336. Consequently, at that time, that NAND gate would develop logic 0 on the conductor 463 — with consequent reversal of the motor 562 and with cancellation of the validation signal on the

conductors 324 and 325. The portion of the switch actuator 164 which extended downwardly through the hole in the bill would keep that bill from being returned to the person who inserted it; and, at the end of the time interval established by the Gross Time Delay Circuit 400, the motor 562 will come to rest. Because the validation signal was cancelled, the paper currency validator would not be able to supply a vend signal to the vending machine.

If a person were to attach a tape or other tail to a bill and then attempt to pull that bill outwardly of the paper currency validator 30 after the sub-circuit of FIG. 11 had developed a validation signal on the conductors 324 and 325, the leading edge of that bill would be moved outwardly of the actuator 164 of the switch 162 while the switch 146 was held closed and while logic 1 appeared on the conductors 324 and 325. At such time, the logic 0 on the conductor 336 would cause the inverter 484 to apply logic 1 to the upper input of the NAND gate 506, the logic 1 on the conductor 352 would appear at the middle input of that NAND gate, and the logic 1 on conductor 324 would appear at the lower input of that NAND gate. Consequently, that NAND gate would apply logic 0 to the conductor 463 — with consequent reversal of the motor 562 and cancellation of the validation signal on the conductors 324 and 325. Hence, that bill and its tape or other tail would be backed out of the paper currency validator 30, and that paper currency validator would not apply a vend signal to the vending machine.

The Bill Retrieval Circuit 504 would cause reversal of the motor 562 and cancellation of the validation signal whether the bill was underlying only the actuator 164 of the switch 162, was underlying only the actuators 164 and 158 of the switches 162 and 156, or was underlying all of the actuators 148, 158 and 164 at the time that person started pulling the bill back out of the paper currency validator. As long as the switch 162 is permitted to re-open while a validation signal is present on the conductor 324 and the switch 146 is closed, the NAND gate 506 will apply logic 0 to the conductor 463 — with consequent reversal of the motor 562 and cancellation of the validation signal.

If a person inserted an elongated object into the paper currency validator 30 and thereby raised the actuator 164 sufficiently to close the switch 162, the motor 562 would start rotating in the reverse direction and logic 0 would be applied to the conductors 324 and 325. Specifically, as the switch 162 was closed, the resulting application of logic 0 to the lower input of NAND gate 334 would cause that NAND gate to apply logic 1 to the upper terminal of capacitor 408 in the Gross Time Delay Circuit 400 and also to the cathode of diode 532 in FIG. 13. The logic 0 on conductor 352 would cause the inverter 446 to apply logic 1 to the middle input of NAND gate 510; and, because the inverter 316 was applying logic 1 to the lower input of that NAND gate via conductor 326, and conductor 336 was applying logic 1 to the upper input of that NAND gate, that NAND gate would apply logic 0 to the conductor 463. The logic 0 on the conductor 422 would be applied to the pin 13 of the voltage regulator 534 in FIG. 14; and that voltage regulator would cause the transistor 554 to supply current to the motor 562, and the Reverse Relay Latch Circuit 518 would energize the reverse relay 468 and thereby cause that motor to start rotating in the reverse direction. Also, the diode

528 would become forward-baised and would inhibit the development of a validation signal on the conductors 324 and 325.

If a person inserts a bill and then halts inward movement of that bill after that bill has closed the switch 146 but before that bill has closed the switch 156, the Gross Time Delay Circuit 400 will energize the motor 562 in the forward direction for the time interval of about 6 to 12 seconds, and then will de-energize that motor. In such event, that person will not be able to injure the paper currency validator 30, and will not be able to cause that paper currency validator to supply a vend signal to the vending machine.

If a person inserts a bill and then halts inward movement of that bill after that bill has closed the switches 146 and 156 but before that bill has closed the switch 162, the Postional Time Delay Circuit 428 will cause the Time Delay Output Circuit 460 to apply logic 0 to the conductor 463. Thereupon, the motor 562 will reverse, and the diode 528 will inhibit the development of a validation signal on the conductors 324 and 325. In such event, the person will retrieve his bill but will not be able to cause the paper currency validator 30 to supply a vend signal to the vending machine.

If a person inserts a bill and then halts inward movement of that bill after that bill has closed the switches 146, 156 and 162 but before a validation signal can be applied to the conductors 324 and 325, the Further Time Delay Circuit 444 will cause the Time Delay Output Circuit 460 to apply logic 0 to the conductor 463. Thereupon, the motor 562 will reverse, and the diode 528 will inhibit the development of a validation signal on the conductors 324 and 325. In such event, the person will retrieve his bill but will not be able to cause the paper currency validator 30 to supply a vend signal to the vending machine.

If a person inserts a bill and then halts inward movement of that bill after that bill has closed the switches 146, 156 and 162 and after a validation signal has been applied to the conductors 324 and 325, the Gross Time Delay Circuit 400 will keep the motor 562 energized in the forward direction for the time interval of about 6 to 12 seconds, and then will de-energize that motor. In such event, that person will not be able to injure the paper currency validator 30, and will not be able to cause that paper currency validator to supply a vend signal to the vending machine.

In some instances, persons have been known to repeatedly pull out and re-insert the line cord of a paper currency validator in an effort to attain an unauthorized operation of that paper currency validator. In the paper currency validator 30, the parallel-connected resistor 514 and capacitor 516 of the Line-Cording Circuit 512 maintain a voltage of about 12 volts at the upper terminals thereof whenever logic 1 is present on the conductor 463. If a person pulls out and re-inserts the line cord plug of the paper currency validator 30, the voltage at the upper terminals of resistor 514 and of capacitor 516 will decrease rapidly, in accordance with the exponential decay curve of that capacitor; and, in a matter of milliseconds, that voltage will decrease to the point where the inverter 520 will coat with the transistor 476 to energize the reverse relay coil 468. Thereupon the movable relay contacts 470 and 472 will shift into their reverse positions; and, if any of the switches 146, 156 and 162 is closed, the diode 528 will inhibit or cancel any validation signal. Even if a

person was able to re-insert the plug for lengths of time that were exactly equal to the lengths of time during which that plug was removed, the voltage at the upper terminals of resistor 514 and of capacitor 516 would decrease; because the initial portion of the exponential decay curve of a capacitor is steeper than the initial portion of the exponential growth curve of that capacitor.

If a person pulls out the line cord plug of the paper currency validator 30, waits a short length of time, and then re-inserts that plug, the voltage across the capacitor 516 will not immediately rise to 12 volts. Instead, because the initial portion of the exponential growth curve of that capacitor is not steep, that voltage will remain low for a long enough period of time to apply logic 0 to the conductor 463. Thereupon the movable relay contacts 470 and 472 will shift to their reverse positions; and, if any of the switches 146, 156 and 162 is closed, the diode 528 will inhibit or cancel any validation signal on the conductors 324 and 325. In these ways, the Line-Cording Circuit 512 of paper currency validator 30 can keep any pulling and re-inserting of the line cord plug from initiating an unauthorized operation of that paper currency validator.

When the line cord plug is again solidly seated within the receptacle therefor, and all of the switches 146, 156 and 162 are open, the voltage at the upper terminals of resistor 514 and of capacitor 516 will begin to rise; and logic 1 will again appear on the conductor 463. At such time, the inverter 520 and the transistor 476 will be unable to keep the relay coil 468 energized; and hence the movable relay contacts 470 and 472 will shift back into their forward positions. Also, the diode 528 will be back-biased; and the conductors 324 and 325 will be capable of having logic 1 applied thereto.

If a person were to paste or tape the left-hand or right-hand half of an authentic U.S. one dollar bill to a piece of paper which had the dimensions of that bill, and if that person inserted that piece of paper into the paper currency validator 30, the leading edge of that piece of paper would be moved inwardly and would successively close the switches 146, 156 and 162. Also, the grid lines in the one-half of the portrait background of that bill would cause the Frequency-Sensing Circuit 280 or 294 to render the transistor 298 or 299, respectively, conductive. However, because both of the magnetic heads 208 and 210 must be engaging vertical grid lines at the same time to enable both NAND gates 312 and 314 to develop logic 1, and because one half of a portrait background is too narrow to span the distance between the air gaps of those magnetic heads, the half-bill can not cause those NAND gates to apply logic 1 to the conductors 324 and 325. Consequently, at the end of the time delay provided by the Further Time Delay Circuit 444, the capacitor 452 and the transistor 458 will render the transistor 462 conductive, and will enable the latter transistor to apply logic 0 to conductor 463 — with consequent reversal of motor 562 and with consequent inhibiting of the development of a validation signal on the conductors 324 and 325. In this way, the mounting of the magnetic heads 208 and 210 of the paper currency validator 30 so they sense the vertical grid lines in diagonally-displaced quadrants of the portrait background of a bill will keep a person from using the left-hand or right-hand half of a bill to effect an unauthorized operation of that currency validator.

The paper currency validator 30 is shown equipped with just two magnetic heads 208 and 210; but, if desired, that paper currency validator could be equipped with additional magnetic heads. Further, if desired, that paper currency validator could be equipped with other testing devices. Any such additional magnetic heads and any such other testing devices would have the validity-checking sub-circuits thereof connected to NAND gates; and each of those NAND gates would have one input thereof connected to conductor 319 and would have the output thereof connected to the conductor 324.

The A. C. generator 560 constitutes an inexpensive and rugged source of feedback for the Amplitude Responsive Control Circuit 533 of FIG. 14. However, various other dynamic feedback sources, and various static feedback sources, could be used in lieu of the A. C. generator 560. All the Amplitude-Responsive Control Circuit 533 of FIG. 14 requires is a supply of feedback which varies the amplitude thereof in response to changes in the speed of the motor 562; and various feedback generators — either dynamic or static in nature — could be used to supply such feedback to that Amplitude-Responsive Control Circuit.

The paper currency validator 30 which is provided by the present invention is small, rugged and inexpensive, but it is accurate and stable in operation. Moreover, that paper currency validator is strongly resistant to efforts of persons to effect unauthorized operation thereof. If desired, the bill-actuated switches 146, 156 and 162 could be replaced by photoelectric switches or other suitable position-sensing switches.

Whereas the drawing and accompanying description have shown and described a preferred embodiment of the present invention, it should be apparent to those skilled in the art that various changes can be made in the form of that invention without affecting the scope thereof.

What I claim is:

1. A validator which comprises a sensing element, means to provide relative movement between an authentic document and said sensing element to develop a signal having a given frequency, and a frequency-sensing circuit which has the essential elements thereof fixed in nature rather than adjustable in nature, whereby said frequency-sensing circuit has greater stability and is less expensive than a comparable frequency-sensing circuit which has the essential elements thereof adjustable in nature, said essential elements of said frequency-sensing circuit helping establish and maintain a predetermined center frequency for said frequency-sensing circuit, and said means having a speed-adjusting sub-circuit which permits the rate of said relative movement to be adjusted to cause said given frequency of said signal to be sufficiently close to said predetermined center frequency to enable said frequency-sensing circuit to respond to said signal.

2. A validator as claimed in claim 1 wherein said means includes an adjustable speed D.C. motor and a feedback loop that keeps the adjusted speed of said D.C. motor substantially constant.

3. A validator as claimed in claim 1 wherein said means includes an adjustable speed D.C. motor and an amplitude-responsive control circuit which is part of a feedback loop that keeps the adjusted speed of said D.C. motor substantially constant, and wherein a feedback generator supplies feedback to said amplitude-

responsive control circuit which has an amplitude that varies with the speed of said D.C. motor.

4. A validator as claimed in claim 1 wherein said means includes an adjustable speed D.C. motor and an amplitude-responsive control circuit which is part of a feedback loop that keeps the adjusted speed of said D.C. motor substantially constant, wherein a feedback generator supplies feedback to said amplitude-responsive control circuit which has an amplitude that varies with the speed of said D.C. motor, wherein said speed-adjusting sub-circuit includes an adjustable impedance to adjust the effective value of said feedback, and wherein said speed-adjusting sub-circuit develops a reference and compares said effective value of said feedback with said reference to produce an error signal which is proportional to any variation between the actual speed and the desired speed of said D.C. motor.

5. A validator as claimed in claim 1 wherein one of said essential elements of said frequency-sensing circuit is a fixed value inductor, wherein another of said essential elements of said frequency-sensing circuit is a fixed value capacitor, and wherein said fixed value inductor and said fixed value capacitor are components of a tuned circuit.

6. A validator which comprises document-moving members that move a document inwardly of said validator, a sensing device that responds to the inward movement of an authentic document relative thereto by said document-moving members to develop a signal, position-sensing means that responds to a document and that senses when said document-moving members move a document inwardly to a predetermined position within said paper currency validator, a timing circuit that responds to the sensing by said position-sensing means of the inward movement of a document to initiate a time period of predetermined duration, and means to reverse the direction of movement of said document-moving members and thereby move said document outwardly of said validator if said sensing device does not develop said signal before the end of said time period.

7. A validator as claimed in claim 6 wherein said position-sensing means senses the inward movement of the leading edge of said document and wherein said sensing device senses a portion of said document which is located rearwardly of said leading edge of said document.

8. A validator as claimed in claim 6 wherein said timing circuit includes a capacitor which experiences a given change in the charge therein during said time period, and wherein an opposite change in said charge in said capacitor occurs, when said sensing device develops said signal, to keep said means from reversing the direction of movement of said document-moving members.

9. A validator as claimed in claim 6 wherein said timing circuit includes a capacitor which experiences a given change in the charge therein during said time period, wherein an opposite change in said charge in said capacitor occurs, when said sensing device develops said signal, to keep said means from reversing the direction of movement of said document-moving members, wherein said means includes a control element with a threshold level, and wherein said means includes a Zener device that requires the voltage across said capacitor to exceed said threshold level of said control

element by a fixed amount before said control element can be actuated.

10. A validator which comprises a sensing element, an electric motor which provides relative movement between an authentic document and said sensing element to develop a signal having a given frequency, a frequency-sensing circuit which has a predetermined center frequency that is essentially the same as said given frequency, a current-sensing sub-circuit that senses the value of the current flowing to said motor, and means that will keep said validator from validating a document if the level of said current sensed by said current-sensing sub-circuit exceeds a predetermined value.

15. 11. A validator as claimed in claim 10 wherein said means includes a selectively-conductive element that can effectively eliminate the output of said frequency-sensing circuit, and wherein said selectively-conductive element of said means will effectively eliminate the output of said frequency-sensing circuit whenever said current-sensing sub-circuit exceeds the level of said current sensed by said predetermined level.

12. A validator as claimed in claim 10 wherein said current-sensing sub-circuit includes an adjustable member which can be adjusted to set said predetermined value, wherein said adjustable member applies a voltage to one input of a comparator, and wherein a voltage corresponding to the current flowing through said motor is applied to another input of said comparator.

13. A validator as claimed in claim 10 wherein said means includes a selectively-conductive element, and wherein said selectively-conductive element does not keep said frequency-sensing circuit from sensing and responding to said given frequency but can effectively eliminate the output of said frequency-sensing circuit.

14. A validator as claimed in claim 10 wherein a speed-regulating feedback loop for said electric motor has amplification therein, and wherein said speed-regulating feedback loop responds to retardation of said document to materially increase the value of the current flowing to said motor, whereby said validator can effectively eliminate the output of said frequency-sensing circuit when even relatively small retardation of said document occurs.

15. A validator which comprises a document-sensing circuit that can respond to the sensing of an authentic document to develop a predetermined signal, an output circuit, a switch that normally can initiate operation of said document-sensing circuit and thereby normally enable said output circuit to develop an output signal, and a circuit that responds to the development of said predetermined signal to effectively isolate said switch from said document-sensing circuit.

16. A validator as claimed in claim 15 wherein an electric motor can provide relative movement between said document and a sensing element, wherein said switch can normally initiate operation of said electric motor, and wherein said circuit effectively isolates said switch from said electric motor whenever it effectively isolates said switch from said document-sensing circuit.

17. A validator which comprises a sensing device, document-moving members that can move a document inwardly toward and adjacent to said sensing device and then can move said document inwardly beyond

said sensing device, means to determine whether said document-moving members have moved said document inwardly beyond said sensing device, and a circuit that can reverse the direction of movement of said document-moving members, said circuit reversing the direction of movement of said document-moving members if said means determines that said document-moving members have not moved said document inwardly beyond said sensing device, said document-moving members providing gripping forces immediately outwardly of said sensing device to enable said document-gripping members to be in register with and to grip the trailing portion of a document which had the major portion of the length thereof wrinkled and crumpled up against said sensing device while said document-moving members were moving said document toward said sensing device.

18. A validator as claimed in claim 17 wherein said means includes a bill-actuated sensing member that senses the inward movement of the leading edge of said bill.

19. A validator as claimed in claim 17 wherein a timing sub-circuit will cause said circuit to reverse the direction of movement of said document-moving members if said means does not, within a pre-set length of time, determine that said document-moving members have moved said document inwardly beyond said sensing device.

20. A validator as claimed in claim 17 wherein said document-moving members are pulley-driven belts, 30

and wherein at least one pulley for each belt is disposed immediately outwardly of said sensing device.

21. A validator as claimed in claim 17 wherein said sensing device must directly engage said document as it senses said document, and wherein the leading edge of said document must force its way between said sensing device and a pressure-applying element which is in register with said sensing device.

22. A validator which comprises document-moving members that move a document inwardly of said validator, position-sensing means that senses when a document is moved inwardly to a predetermined position within said paper currency validator, further position-sensing means that senses when said document is moved further inwardly to a second predetermined position within said paper currency validator, a sensing device located intermediate the first said and said further position-sensing means and that can respond to the inward movement of an authentic document relative thereto by said document-moving members to develop a signal, a timing circuit that responds to the sensing by the first said position-sensing means of the inward movement of a document to initiate a time period of predetermined duration, and means to reverse the direction of movement of said document-moving members and thereby move said document outwardly of said validator if said further position-sensing means does not sense the inward movement of said document before the end of said time period.
